GEORGE E. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

ART OF MAKING SHOES.

Application filed June 11, 1921. Serial No. 476,659.

This invention relates to the manufacture of shoes. An important general object of the invention is to provide a method by which to effect in shoemaking radical and far-reaching economies and by which to produce at the same time shoes of uniformly excellent quality.

It is peculiarly characteristic of shoe manufacture that success in the performance of each of a great number of distinctly different and complicated operations involved in the making of a shoe is dependent upon the proper performance of earlier operations. Also, notwithstanding the striking advances made in shoemaking, especially during the last two decades, it nevertheless is still conspicuously true that shoemaking involves many operations which absolutely require and depend for success upon the exercise of great skill, care and judgment by the workmen. It follows that under present conditions the manufacture of shoes necessarily entails a heavy labor cost. Furthermore, even under the most favorable manufacturing conditions and with the exercise of the greatest skill and care obtainable from thoroughly competent workmen, shoemaking operations are frequently performed inaccurately so that one or more of the later operations in the manufacture of a given shoe are rendered difficult or impossible of satisfactory performance, often resulting in damaged or crippled shoes requiring expensive repairs to correct the damage, so far as it can be corrected. In many instances, failure to perform various shoemaking operations successfully may be traced directly to failure on the part of workmen to locate or position shoes or shoe parts properly for one or more operations, such locating in many cases being determined largely by the eyes or fingers of the workmen. Such errors in location are especially serious in that they are typical of errors which may have a cumulative effect as the shoes go through the factory and result in damaged or unsalable shoes.

In view of the above-named and other conditions, a striking characteristic of the present invention consists in provision for standardization of shoe parts and shoemaking operations. In one important aspect this is accomplished by procedure, in the preparation, assembling and treatment of shoe parts or units, which may be conveniently, and is

herein frequently, termed "jigging", to position the parts or units in predetermined relation to each other or to means for operating upon them. That is to say, as herein exemplified, units of a shoe are each provided with one or more positioning surfaces bearing a predetermined relation to the contour or some other characteristic thereof. Such surfaces are or may be used to control the positions of the units in preparing or shaping the units separately, and such surfaces are utilized to control the positions of the units in predetermined relations to each other in making the shoe. This provides for the preparation of standardized, interchangeable parts or units which may be separately accumulated, if desired, and for utilizing those units in the making of shoes quickly, accurately and uniformly and without requiring any substantial skill.

Important results of such standardization are that successive shoemaking operations are each performed so accurately as to prepare the shoe parts or the shoes in the best manner for the satisfactory performance of later operations, and uniformity of the shoemaking operations and consequent uniformity of the product are insured at greatly reduced labor cost. The reduction of the labor cost is largely due to the fact that skilled labor may be reduced to a minimum in the manufacture of shoes. Moreover, while many of the striking advantages and economies of the present invention may be otherwise obtained, the shoe making procedure herein set forth lends itself readily to extensive use of automatic machinery. The present invention also effects great economies in shoe materials, particularly in leather, because its use minimizes the waste which results, under present shoemaking methods, to a large extent from the necessity of cutting various shoe parts substantially larger than they are ultimately to be in order to allow for errors and adjustments by the workmen.

In another aspect, the invention provides for great economies in the expense necessary for lasts and other equipment. Under the present practice, shoe parts are assembled on the lasts early in the manufacture of the shoes, and the shoes remain upon the lasts substantially throughout the shoemaking. Moreover, as shoes are now made, it is generally necessary to allow considerable time

at different stages in the shoemaking for the shoe materials to set in order that the shoes shall permanently retain the desired shape. For example, in the manufacture of Good-
 5 year welt shoes, a given shoe commonly remains on its last from one to two weeks. Such shoemaking not only requires a very large stock of lasts, but necessitates extensive storage space in the factory, both for the
 10 shoes and shoe parts in process and also for the lasts, shoe racks and other equipment. For the purpose, among others, of effecting economies in these respects, the present invention provides for carrying the preparation and assembling of shoe units to an advanced stage before the introduction of the last. As herein exemplified, minor shoe units are assembled into a comparatively few major units, and the shaping of various units
 15 20 as required for the finished shoe is largely completed before the units are mounted on the last, thus greatly reducing the length of time the shoes must remain upon their lasts.

The general nature and purpose of the invention having been thus indicated, it will now be described in detail by reference to the accompanying drawings and will then be defined in the appended claims.

In the drawings, which illustrate diagrammatically successive steps in the preparation of the several units and in the assembly thereof to complete the shoe and which illustrate also diagrammatically certain devices or apparatus which may be utilized for performing these steps,

Fig. 1 is a view in perspective of a vamp of a shoe upper and of a die which may be used for cutting it out from a skin and also at the same time punching jig holes and forming slits in the vamp in accordance with the preferred manner of practicing the invention;

Fig. 30 is a perspective view of the heel 10 at the stage in its preparation represented in Fig. 29;

Figs. 31 and 32 are two views in sectional elevation illustrating successive steps in the slugging of the heel;

Fig. 33 is a similar view illustrating the step of trimming and breasting the heel;

Fig. 34 is a similar view illustrating the heel while being finally compressed;

Fig. 35 is a perspective view of the complete heel ready for attachment to the shoe;

Fig. 36 is a sectional elevation of the shoe unit shown in Fig. 16 with a two part last partially inserted therein;

Fig. 37 is a similar view showing the last 25 fully inserted, its two parts being locked together;

Fig. 38 is a sectional elevation of the assembled shoe and last illustrating the step of side lasting;

Fig. 39 is a detail view in perspective showing the seam by which the upper is secured to the insole during such lasting;

Fig. 40 is a perspective view of the shoe after the side lasting is completed;

Fig. 41 is a similar view of the shoe after the welting operation and after a part of the inseam has been trimmed;

Fig. 42 is a sectional elevation illustrating the step of stitching the outsole to the welt 40 after the outsole unit has been assembled upon the shoe;

Fig. 43 is a similar view illustrating the step of leveling the sole;

Fig. 44 is a perspective view illustrating the steps of butting the welt and outsole of the shoe;

Fig. 45 is a similar view of the shoe immediately after said butting operation;

Fig. 46 is a sectional elevation illustrating the step of permanently attaching the complete heel to the shoe shown in Fig. 45;

Fig. 47 is a perspective view illustrating a step in the finishing of the heel;

Fig. 48 is a sectional plan on the line A—A, 55 Fig. 46, showing the joint between the heel, outsole unit and welt;

Fig. 49 is an inverted plan, showing the relative location of the several kinds of fastenings at the heel end of the shoe;

Fig. 50 is a side elevation of the shoe when finished.

The invention is herein exemplified with special reference to the manufacture of Good-year welt shoes which are generally recognized as the best type of shoes made but it is

to be understood that, in various aspects, the invention is not limited in its application to welt shoes or to any other particular types of shoes.

As the invention is herein described by 70 way of illustration, the insoles are made exact and uniform in size and shape and also in the position of the sewing rib and the uppers are molded at the heel and toe ends to correspond to the shape of the last and are then 75 secured in exactly the correct relation to such prepared insoles, all preferably before these parts are assembled on the manufacturing last. The bottom foreparts also are separately manufactured as units, each usually including an outsole, a filler and shank stiffener and each being of predetermined size and shape. Similarly, the heels are built up and the manufacturing processes thereon carried to an advanced stage before attachment to the 80 shoes. For each shoe, a set of these parts as distinct units, viz, an upper and insole, preferably secured together, an outsole unit and a heel are assembled and permanently incorporated in the shoe. Such assembling, according to that method of practising the invention which is now considered best, is performed upon a divided collapsible last which may be expanded slightly to stretch the upper and the rear part of which may be removed when, as is contemplated, the heel is to be attached by nails driven from the inside of the 85 shoe.

To facilitate speed and accuracy in preparing the units, in assembling these units on the last or other suitable support, and in the further manufacture of the shoe, the invention makes special provision, as has already been indicated, for the jiggling of the parts and units with relation to one another and with 100 relation to the instrumentalities by which successive operations on the shoe or shoe parts are to be performed. For example, the different sole and heel units may each be provided with one or more positioning surfaces 105 by the aid of which said units are assembled accurately in the shoe and which also facilitate the preliminary manufacturing of said units with accuracy. As another illustration, different parts of the upper are preferably 110 provided with complementary positioning surfaces, which advantageously may be in the form of jig holes within the margin of the upper and which are utilized for correctly locating the parts not only with relation to each other but also for shaping, molding, or otherwise operating upon the parts.

Referring now to the preferred manner of practicing the complete method of making shoes which is the subject of this application and certain steps of which are illustrated in the accompanying drawings, apparatus which may conveniently be utilized in performing such steps is shown, but only more or less diagrammatically or conventionally 115 120 125 130

because the apparatus itself forms no part of the invention herein claimed, but is being made the subject of a series of co-pending applications for Letters Patent of the United States, some of which are hereinafter mentioned. Moreover, while the carrying out of the method is not dependent upon any particular apparatus and, indeed, may be performed largely by hand with the aid of simple apparatus, such as molds, yet the present invention is particularly adapted for use in connection with automatic machinery as will be further explained.

The steps of preparing the several major or principal units of the shoe before they are mounted on the manufacturing last will now be described.

Beginning with the preparation of the "upper," the assembled upper materials, commonly referred to herein and in the shoe trade as the "upper," may comprise the ordinary elements including, for example, the leather or cloth upper itself, the lining, and usually also a counter and a box toe of the ordinary or any suitable type. It is contemplated that when a box toe is used it will be of that common type which is readily softened by heat and which hardens quickly as it cools. Such a box toe while soft and moldable is preferably inserted between the tip and lining of the upper after which the entire toe will be molded to substantially its final shape in the manner shortly to be described.

The upper proper and the lining may be died out nearer to its final outline than has been previously the practice largely because of the fact that both the toe and heel are molded. The upper 1 shown in the drawings includes a full vamp 2 which is provided, as shown in Fig. 1, with one pair of jig holes 4 adjacent to both its tip line and its margin and also with two pairs of similar jig holes 6 near its rear end. The upper comprises also a tip 8 (Fig. 2) having a pair of jig holes 10 to match the jig holes 4 and may also include a top 12, as shown in Fig. 16, which is sewn to the vamp in any usual or suitable manner. If preferred, the front of the vamp may be cut with extensions or tabs 14, as indicated in dotted lines in Fig. 1, and the jig holes 4 may be formed therein so that the holes shall be substantially forward of the location where the tip seam is to be stitched, as will be explained.

As illustrated in Fig. 1, the jig holes 4 and 6 are formed in the vamp 2 at the same time that it is died out from the skin, the vamp die 16 being provided with suitable punches 18 for that purpose, with the result that these holes are located in exact predetermined relation to the periphery of the vamp. The jig holes 10 are preferably located in the tip 8 in a similar manner at the time that it is died out.

Moreover, it is desirable to provide the opposite sides of the marginal portion of the vamp with inwardly extending slits as indicated at 20 adjacent to the points at which the inseam, as well as the insole rib, is to begin and end for a purpose hereinafter explained. Advantageously these slits may be produced also during the dieing-out operation, as for example, by blades such as 22 secured to the vamp die 16, as indicated in Fig. 1.

The design with respect to style and size of the particular shoe to be manufactured having been selected, the locations of the jig holes, such as 4, 6 and 10, and of the slits such as 20 in the upper, are determined by the designer not only with relation to each other and to the pattern, or shape, of the upper but also with relation to certain co-operating jig holes, jig pins or other positioning surfaces provided, as hereinafter explained at predetermined locations both in the instrumentalities which shape or otherwise operate upon the upper and also in other elements of the shoe which are to be assembled with and secured to the upper, all in such a manner that the various cooperating parts or units of the shoe shall fit accurately together and result in a uniform product of standard measurement and shape corresponding exactly to the selected design and yet eliminating the need of special skill on the part of the workmen. Advantageously and as illustrated in the accompanying drawings the jig holes as well as the slits are formed in such portions of the upper that they will be unexposed in the shoe when finished, and, indeed, in portions which may, in some instances, be trimmed off during the manufacture of the shoe. Likewise, as already indicated, the jig holes 4 and 10 are conveniently located at opposite sides of the shoe in the vicinity of the tip seam while the front and rear holes 6 in the heel portion of the upper are spaced a substantial distance apart and at such locations, both heightwise of the upper and angularly relatively to each other respectively, that the upper in the shoe when finished shall have a predetermined height and shall fit the last, and hence the foot, smoothly and accurately. Jig holes may be formed in the lining corresponding in size and location to the jig holes 4 in the vamp but preferably still larger openings or notches are formed in the lining to provide ample clearance for the jig pins 134, below mentioned.

The jig holes thus provided in the tip and vamp are utilized in locating the parts precisely in correct relative position when the tip and vamp are being secured together and when the vamp is closed or back seamed. For example, Fig. 2 illustrates a part of a machine which may be used in stitching the vamp and tip together and, particularly devices connected with that machine for correctly locating the vamp and tip longitudi-

nally, laterally and angularly for that operation. As shown, 26 represents a movable work carrier comprising relatively movable clamps 28, 30 between which the work is firmly held during the stitching operation. Clamp 28 is provided with a pair of jig pins 32 rounded somewhat at their upper ends but otherwise of a size to fit the jig holes 4 and 10, respectively, in the vamp and tip. While the clamp is open, the vamp and tip are successively located upon the work carrier by slipping the holes 4 and 10 over the upstanding pins 32, whereupon the clamp 30 is lowered to maintain the parts securely in the position thus determined. The upper being thus clamped in the work carrier, the latter is moved progressively past the stitching instrumentalities so that the tip seam is sewn in a predetermined path. If desired, the 20 jig pins 32 may be withdrawn after such clamping and stitching begins as shown at the right in Fig. 2. While machines of various types may be utilized for performing this step in the present method, a machine of the 25 automatic type which may be used advantageously for thus locating and stitching the tip seam is disclosed and claimed in a copending application filed in the name of Benjamin F. Mayo which has now matured as 30 Patent No. 1,569,232, granted Jan. 12, 1926. For the purpose of the present application it is sufficient to state that, as illustrated herein, the work carrier 26 is provided with a pair of guide rolls 34 which engage a cam track 36 35 formed in a member secured to the head of the stitching machine which is indicated conventionally by needles 38. It will be noted that, by this method of jiggling, not only are the vamp and tip invariably located in correct 40 relative position but they are presented to the stitching instrumentalities in such a manner that the tip seam is located in exact predetermined relation to the jig holes and therefore to the rear edge of the tip.

45 Under certain conditions and especially when a vamp without the tabs 14 is used, it may be preferred to cement the tip and vamp together, in which case the parts will be correctly located by jig pins, such as 32, in the 50 manner described and then the overlapping cemented surfaces will be pressed together, after which the tip seam may be stitched as shown in Fig. 2 but, because the parts are cemented together, it will suffice if the clamps 55 28, 30 engage the tip only.

For insuring the correct positioning of the upper for the closing or stitching of the back-seam 40, the upper may be folded inside out on its longitudinal median line and placed in 60 a carrier 42 forming a part of a stitching machine, two jig pins 44 in the carrier fitting within and serving with certainty to align corresponding pairs of holes 6 on opposite sides of the vamp, as shown in Fig. 3. Thus 65 said jig pins and jig holes locate the upper invariably in correct position in the carrier 42 in which position the upper is clamped, as by a member 46 pivoted to the work supporting plate of the carrier. As shown, the latter is provided with two guides 48 fitting a cam track 50 formed in a member secured to the head of the stitching machine, indicated conventionally by the needle 52. By the use of the mechanism just described, the upper, after it has been correctly positioned in the carrier, 70 is guided in a predetermined path during the relative travel of the carrier and the stitching instrumentalities so that the back seam 40 is invariably located exactly in the same position with respect to the jig holes in the upper and to the tip seam. One machine of the 75 automatic type which may be used for stitching the back seam in the manner just indicated forms the subject of a copending application Serial No. 368,025, filed by Benjamin F. Mayo, on March 3, 1920.

In addition to other functions of the jig holes 10 in the tip herein referred to, these holes together with complementary jig pins 80 may be utilized in a similar manner to jig the 90 tip with relation to a die or machine for producing ornamental perforations in the tip. Such perforations are shown in Fig. 3, for example, but are omitted in Fig. 2 in order that the jig holes 10 may be shown more clearly. 95

Turning now to the preparation of the insole, Figs. 4 to 7 illustrate a type of insole and also successive steps in its manufacture, which form a part of the present invention. As shown, the insole 54 is made up of two or 100 more layers of fabric or other suitable material including a layer 56 of canvas in which a stitch receiving rib or lip 58 is molded and to which the other layer or layers 60 are adhesively secured. If desired, the upper or 105 foot engaging layer may be of a material, such as pantasote, which presents a relatively smooth surface along which the foot will slide easily and which has an appearance somewhat resembling leather. Outside of the rib 110 58, the insole has the usual feather 62 which is preferably depressed or offset around the toe, as at 64, particularly when a box toe is employed, to compensate for the additional thickness of the upper materials at that point, 115 and thus to facilitate the location of the inseam at a uniform distance from the unribbed face of the insole. Similarly the margin may be depressed around the heel end, as at 66 to compensate for the thickness of the counter. In predetermined relation to the rib 58, 120 the insole is provided with two circular jig holes 68, preferably spaced apart a predetermined distance and located in the longitudinal median line of the heel portion of the insole. However, the rear hole may be elongated as indicated in dotted lines, if desired, to facilitate placing it over the jig pins hereinafter mentioned.

In manufacturing such an insole commer- 130

cially, it is contemplated that the several layers will be died out and that then through the operation of a substantially automatic machine, such, for example, as one already 5 invented by Frederick H. Perry and disclosed and claimed in a copending application, which has now matured as Patent No. 1,667,948, granted May 1, 1928, the rib 58 will be formed in the layer 56, the other layer 10 or layers 60 will be located accurately in predetermined relation to the layer 56 and then secured permanently thereto by adhesive and under pressure. However, so far as the broad features of the present invention are 15 concerned, the insole may be built up in a variety of ways and with the aid of simple molding instrumentalities, such as are illustrated diagrammatically in Fig. 4, wherein a female mold 70 is provided with a groove 72 corre- 20 sponding in outline and depth to the rib 58 to be formed in the layer of canvas 56. In order to produce in the margin of the insole the depressed portions 64, 66 above described, the end marginal portions of this mold 70 are 25 made somewhat higher than its general surface, the adjacent horizontal surfaces being joined together by short, inclined surfaces 74, 76. The male mold 78 is provided with molding surfaces complementary to those of 30 mold 70, including a rib 80 shaped to press a portion of the layer 56 firmly into the groove 72. After the ribbed layer 56 has been molded as shown in Fig. 4, the other layer or layers 60 are deposited upon and in predetermined 35 relation to the ribbed layer, adhesive having been previously applied to at least one of each two adjacent layers in any suitable manner, and then all the layers while supported by mold 70 are held under pressure by a mold 40 similar to the mold 78, but without a rib such as rib 80, until the adhesive has dried sufficiently to insure a permanent connection between the layers. This stage in the process is illustrated in Fig. 5. Under certain circumstances, it may be preferable to secure two un- 45 ribbed layers together permanently and apply them as a unit to the ribbed layer 56. Next, according to the manner of practicing the invention herein exemplified, the margin 50 of the insole is trimmed and two jig holes 68 are punched to insure that its periphery and the holes shall be in predetermined relation to each other and to the rib 58. For performing these operations a rounding machine of 55 the well known Planet type, modified as indicated in Fig. 6, may be employed. As shown, a sole support and pattern 82 has a marginal upstanding rib 84, the inner wall of which is constructed and arranged to fit accurately the 60 outer side of the rib 58. The upper surface of the rib 84 has a width complementary to the feather or margin of the insole and constitutes a support for the insole which is clamped between the rib 84 and a clamp plate or block

86. With the insole thus located and 65 clamped, it is trimmed around its periphery by a knife, indicated at 88, which bears against and is guided by the outer face of the rib 84. Also, as shown, while the insole is thus clamped the jig holes 68 are formed by 70 suitable punches one of which is indicated at 90 and each of which is guided by an opening 92 in the pattern and cuts against the block 86. It should be noted that the insole is thus 75 jigged for the trimming and punching operations so that its final periphery is at every point located at a predetermined distance from the outside of the rib and so that the jig holes 68 are likewise located at predetermined distance from the outside of the rib 80 and from the periphery of the finished insole as shown in Fig. 7.

Preferably a heel reinforce or plate 94, such as shown in Fig. 10 is applied to the inside of the insole, or, it may be, between its layers, 85 during the course of the manufacture of the shoe, for the purpose of providing sufficient holding means for the clinched points of the heel seat lasting tacks and for the heads of the heel attaching nails, as will further appear. 90 This heel reinforce may be made of any suitable hard, tough material, such as fibre-board, and is preferably given a curvature corresponding approximately to the bottom of the heel portion of the last and its edges 95 are beveled as shown at 96, 98. It is also provided with two jig holes 100 corresponding exactly to the jig holes 68 in the insole.

One way of preparing this heel reinforce is illustrated diagrammatically in Fig. 9, 100 wherein is shown a pair of molds 102, 104 having complementary molding surfaces so shaped as to produce the transverse and, it may be, the longitudinal curvatures desired in the finished heel plate. While it is under pressure between the molds the plate is cut to the predetermined size desired, as for example, by a hollow knife 106 which is guided in vertical trimming movements by the periphery of the mold 102. The plate is preferably of such material that, after it has been molded to the shape shown in Fig. 9, its elasticity will cause it to flatten out somewhat as the pressure of the molds is released and thus the edge 96 will be inwardly inclined with 115 respect to the vertical axis of the plate so that when the reinforce is applied to the last, as below explained, this edge 96 will present a surface which is substantially a continuation of the lateral surface of the last and which, 120 therefore, will fit closely against the adjacent portion of the shoe when incorporated therein. While the reinforce or plate is thus positioned by the molds and knife, a pair of vertically movable punches, indicated at 108, 125 cut out the jig holes 100 so that these holes bear a predetermined relation to the trimmed periphery of the reinforce and correspond ex-

actly with the jig holes 68 in the insole. The bevel 98 is cut at any convenient stage in the manufacture of the reinforce.

Fig. 8 represents a molded counter 110 of a known type which, it is contemplated, will usually be incorporated in the shoe and which is provided with an inturned flange 112, the forward ends of which have up standing wings or margins 114 separated from the flange 112 by slits 116 and so shaped that the angular portions thus formed in the counter fit the angle formed by the rib 58 and the feather 62 of the insole, as shown, for example, in Figs. 13 and 38. In preparing such a counter, it is molded in accordance with known methods to give its sides, flange 112 and wings 114 substantially the shape they are to have in the finished shoe. To facilitate the exact positioning of the counter 110 in correct relation to the other parts of the shoe, as will be hereinafter explained, the counter may be provided, at the time the slits 116 are formed, or at any other convenient stage in its preparation, with one or more positioning surfaces, formed, for example, by a notch 117, cut in the flange 112 in predetermined relation to the contour of the counter and to slits 116.

As already pointed out, an important characteristic of the particular mode or practicing the method herein described, by way of illustration, is that the toe and heel of the upper are molded or shaped off the last to produce the final shape desired in the shoe when finished and to produce inturned flanges which determine the junction of the sides and bottom of the upper and which flanges also, in the case of a welt shoe, terminate in up standing marginal flanges shaped to fit the rib of the insole around the toe.

This molding of the upper may be effected by any suitable instrumentalities, such, for example, as those which are illustrated, largely diagrammatically, in Figs. 11 to 15 of the drawings. Referring particularly to Figs. 11 and 12, which illustrate the molding of the toe of the upper, 118 designates an internal, metallic form or mold having an exterior shape corresponding to the shape which that portion of the toe of the upper which will be visible in the finished shoe is to have. The upper margin of the mold is recessed at 120, as shown in Fig. 12, for a purpose to be more fully described. A pair of laterally movable wipers 122 are actuated during the molding operation to force a portion of the upper adjacent to its margin into the recess 120 as will be more fully described. Preparatory to the molding operation proper, the margin of the outspread toe of the upper is clamped upon the upper face of the wipers 122 by a clamping plate or plates 124, while a yieldingly pressed pad 126 may be employed to clamp the upper against the crowning portion of the mold 118. A rotary trimming knife 128

carried by a shaft 130 is provided for cutting the surplus of the upper at its margin after the upper has been molded.

As already pointed out, an important characteristic of the present invention is the jigging of the upper for molding by positioning it always and without fail in predetermined relation to the molding instrumentalities and then continuing the control of the upper during the molding operation so that the shape, length, lateral and angular positions of the molded portion of the upper will be determined with invariable certainty, and so that all such molded portions of uppers of the same size and style shall be essentially identical and uniform and, moreover, without requiring any substantial exercise of skill or care on the part of the workman on the shoe. Accordingly, as illustrated in the drawings, the toe of the upper is thus located relative to the molding instrumentalities by the use of a presenter 132 having upturned ends in the form of pins 134 which fit respectively the alined jig holes 4 and 10 in the vamp and tip. Shoulders may be provided upon the presenter to limit the distance that the upper may be pushed over the pins. With the upper supported in the presenter, as illustrated in Fig. 11, and with its lining uppermost, and, if desired, with a softened box toe inserted between the lining and the leather tip, the toe which is outspread and substantially flat is laid upon the wipers 122, the pins 134 entering slots 138 in the wipers and being pressed firmly against the inner ends of the slots while shoulders 136 slide beneath the wipers. Thus the upper is jigged or located unerringly with respect to the molding instrumentalities without any skill or judgment being required on the part of the workman.

Thereafter the margin of the upper is clamped by the plate 124, the presenter 132 is removed and the actual molding begins. Thus, the form 118 is moved from a position above the wipers 122 and the plate 124 into engagement with the upper thus clamped, the pad 126 then holding the upper against displacement about the form, the latter continues its downward movement, and gradually withdraws the upper from between the wipers and the plate after which the plate is raised and the wipers are moved inward to force the upper into recess 120, thus forming at the margin of the upper an inturned flange 140 and an upstanding margin 142 shaped to fit the rib 58 of the insole 54 around the toe (Fig. 36), as already suggested. The upper is held under the pressure of the molding instrumentalities until it has become set and during that time the surplus 144 at the margin is removed entirely or partially by rotation of knife 128. Preferably and as shown, for example, in Figs. 16 and 40, this trimming begins and ends slightly forward of the tip seam and of the rear portion of

the molded toe in order to insure that, after the step of side lasting about to be described, during which the margin of the upper is engaged and pulled by grippers, there shall be 5 no portion of the upper in the vicinity of the tip seam which has not been fully shaped and fitted to the last.

A complete machine, designed particularly for molding and trimming the toe of an upper 10 in the general manner just described, is disclosed fully and claimed in a copending application filed in the name of William C. Baxter, which has now matured as Patent No. 1,692,284, granted November 20, 1928, 15 and while this step in the present method may be performed in various ways, the best way now known to applicant involves the use of apparatus of the type disclosed in said application.

20 The heel portion of the upper is molded preferably after the molding of the toe and preferably, also, although in the broader aspects of the invention not necessarily, the insole 54 is permanently secured to the upper 25 as a part of the heel molding operation. As illustrated in Figs. 13, 14 and 15, the heel portion of the upper is molded over a metallic, internal form or mold 146 from which projects a pair of jig pins 148 corresponding 30 in location to the jig holes 68 in the insole 54 and the jig holes 100 in the heel reinforce 94. This form 146 is so shaped as to give the heel portion of the upper substantially 35 the shape which it is to have in the shoe when finished.

As previously pointed out, an important characteristic of the present method is that the parts which are assembled during the heel molding operation are jigged, or positioned with certainty in predetermined relation not only with respect to the molding instrumentalities but also with respect to each other before they are secured together. To accomplish this result, first the reinforce 94 45 is placed upon the form 146 and then the insole 54 is placed upon the reinforce with the jig pins 148 extending through and fitting the jig holes in the heel reinforce and the insole. Then the upper is placed around the 50 form 146, the counter 110 being inserted between the lining and the upper proper, the lining being drawn smooth and over the heel portion of the insole. Because the counter has been initially molded, as described, to fit 55 the manufacturing last and, therefore, the corresponding form 146, and because its upstanding margins 114 have been shaped to fit the rib 58 of the insole, its consequent tendency to locate itself in the correct relation 60 to the form 146 and therefore to the insole as it is pressed about the form and against the insole may, in most cases, be relied upon to insure its accurate position with respect to the other parts of the shoe which are connected with it, as a part of the heel molding

operation. It is contemplated, however, that, under some manufacturing conditions, a molded counter of the same shape may be employed for both right and left shoes so that, as a result of its separate molding, prior to the molding to which it is subjected at the time that the heel portion of the upper is molded, it may not fit both the right form 146 and the complementary left form exactly. In that and other cases, the counter may be 70 positioned with still greater certainty by the method indicated in Fig. 14, in which a thin metal bar 150 is pointed at 152 to fit the notch 117 in the flange 112 of the counter and provided with a pair of jig holes 154 shaped to 80 fit over the jig pins 148 of the form 146. After this bar 150 has served the purpose just stated and after the heel molding operation, it may be removed.

The parts of the heel portion of the shoe 85 having been thus assembled as shown in Fig. 14 with the vamp upstanding around the form 146, a presser foot 156 which is recessed slightly to receive the bar 150 and which is also provided with jig holes to fit the jig pins 90 148 is brought down upon the flange 112 of the counter. This foot carries four jig pins 158 (of which one is hidden in Fig. 15 by other parts) which are relatively so located that the jig holes 6 in the vamp fit over these 95 pins with the result that the heel portion of the upper is thus jigged or located precisely and with certainty with relation to the heel molding instrumentalities. The jig pins 158 are movable laterally and are connected with a relatively movable section 160 of the foot 100 156 so that they are projected outward as shown in Fig. 15 during the downward movement of section 160 after the foot 156 proper has come into contact with the counter, lining or insole. Then, a heel band 162, complementary in shape to the internal form 146, is pressed firmly against the outer side of the upper, imparting to it the shape of the form. After the upper has been clamped, the section 160 is lifted relatively to the foot proper 105 and thus causes the jig pins 158 to be withdrawn from the jig holes in the upper and the foot is moved out of the way to permit the molding of the heel portion of the upper to 110 be completed. Wipers 164 are then moved inwardly to form an inturned flange 165 on the upper, thus producing a sharply defined line 166 between the sides and bottom of the upper. The upper and adjacent parts are 115 held under molding pressure for a time sufficient to permit them to set and, while so held, a series of tacks 168 are driven through holes 170 in the wipers and through the flange 165, the insole 54 and the heel reinforce 94, 120 and are clinched upon the inside of the reinforce by the upper face of the metallic form 146. Thus the flange 165 of the upper is 125 permanently secured to and around the heel portion of the insole by a series of tacks inserted 130

at one operation and in a predetermined relation to each other and to the jig holes 68. The insole and upper thus connected and shown in Fig. 16 represents one of the units 5 of the shoe, herein referred to as major units, which may be separately prepared prior to the assembling of the shoe upon the last. While the operation of molding the heel portion of an upper and securing it to an insole 10 and other shoe parts may be performed in various ways with apparatus of known types, a complete machine which has been particularly designed for the purpose forms the subject-matter of a copending application filed 15 in the name of William C. Baxter, which has now matured as Patent No. 1,700,970, granted February 5, 1929.

The preparation of another of the major units just referred to, viz, the forepart of 20 the shoe bottom, will now be described. As shown in Fig. 23, this bottom unit comprises a short outsole 172, a metallic shank stiffener 174 and a sheet filler 176 permanently secured together in predetermined relation 25 with each other. A bottom unit of this general character and a method of making it form the subject-matter of a copending application in the name of Frederick M. Furber, which has now matured as Patent No. 30 1,582,259, granted April 27, 1926.

As herein shown, the outsole 172 is of a length to extend somewhat back of the breast line of the heel (Fig. 47). As illustrated in Fig. 17, the outsole may first be died out from 35 a hide of leather in the ordinary manner to approximately its final peripheral shape by the use of a die, such as 178. The outsole is also provided in any suitable way with a jig hole 180 adjacent to the rear edge of the outsole and so located that when, at a later stage 40 in the method, the outsole is assembled with its edge in exactly the correct relation to a welted shoe, this jig hole 180 shall align with the forward jig hole 68 of the insole. Mechanism shown in Fig. 18 for thus punching 45 the jig hole comprises a support 182 from which project abutments 184 against which the rear edge of the outsole is firmly pressed. The outsole is centered laterally by side gages 50 177 provided with arms 186 geared together and then the hole is cut out by a punch 188.

In the making of certain types of shoes and as herein exemplified, the sole is next "molded", that is to say, it is given while in temper, or moist, longitudinal and transverse curvatures corresponding approximately to the curvatures of the bottom of the last, so that it, with the parts to be attached thereto, shall fit the bottom of the welted shoe. To facilitate the subsequent stitching operation, the outsole is also molded so as to flare in the shank, as indicated especially in Fig. 43. The molding operation may be performed with the aid of a sole molding machine of usual 65 type. In Fig. 19, where this step is illustrat-

ed diagrammatically, the molds are designated 192 and 194, respectively and the complementary portions for producing the flare just referred to are indicated at 195. According to this invention, the lower or supporting 70 mold 192 is provided with a jig pin 196 over which the jig hole 180 in the outsole is placed, thus locating the rear portion of the outsole exactly both transversely and longitudinally 75 with respect to the molds. The toe end of the outsole may be located transversely in any suitable manner to secure such a degree of accuracy as is useful under actual commercial conditions, as, for example, by utilizing the sides of the lower mold as a gage or, as shown, 80 by a fork 198 which has a predetermined transverse position relative to the molds but may yield longitudinally.

The next step may be, and according to the particular method illustrated is, to trim 85 the outsole since the peripheral shape imparted to it when died out as illustrated in Fig. 17 may be somewhat distorted by the molding operation. The trimming may be effected, for example, by the use of an apparatus of the general character of that shown in Fig. 6 for trimming the insole and comprising, as shown in Fig. 20, a pattern 200 and a clamp 202 each of which within its periphery is hollowed out at 204, so that the 90 outsole is clamped at its margin only, in order not to alter permanently and substantially the shape which was imparted to it in the molding operation indicated in Fig. 19. Likewise, also, substantially all of the moisture 95 in the outsole is allowed or caused to evaporate prior to this trimming operation. In locating the outsole upon the pattern 200 the jig hole 180 in its rear portion is placed over a pin 206 projecting from the pattern. The 100 toe end of the outsole may be positioned transversely, before it is clamped, with the needed degree of accuracy in any suitable manner, as has been just pointed out in connection with the molding operation. Then 105 the outsole is clamped between the parts 200, 202 and a knife 208 is moved around the outsole being guided by the edge of the pattern, thus removing any surplus 210 from the margin of the outsole. However, it may be practicable under particular manufacturing conditions to dispense with either or both of the 110 trimming operations, indicated in Figs. 17 and 20, particularly since it is contemplated that the outsole will be trimmed slightly 115 after it has been stitched to the welt, as below explained. Moreover, cut outsoles as sold in the open market may be punched as indicated at 180 and may then be presented immediately to the molding devices shown in 120 Fig. 19 without any other trimming.

It is contemplated that heels of identical dimensions may be used with outsoles of different thicknesses and, therefore, since the rear portion of the outsole will overlap the 130

front portion of the heel, as shown in Fig. 46, it is skived to a thickness corresponding to that of the thinnest outsole to be used with the same sized heel. Therefore, the next step 5 in the preparation of the outsole, as herein exemplified, is to reduce its rear end to this definite thickness, as indicated at 212 and, at the same time, to reduce the thickness of the edges of the outsole at the shank, as indicated at 213. These operations are indicated in Fig. 21 which shows diagrammatically certain elements of a skiving machine of the well-known "Monarch" type in which the article to be skived is forced by a presser 10 roll 214 into the matrix of a co-operating roll 215 and fed past a knife 216. The outsole may be located with the desired degree of accuracy in relation to the skiving mechanism in any suitable manner. The preferred 15 manner illustrated, however, which also may be employed in positioning a sole or other shoe part for other manufacturing operations, utilizes a jig which is shown more or less diagrammatically in Fig. 22, where 217 20 designates a sole carrier, the opposite side edges of which are fitted to slide in a guideway (not shown) which forms a part of the skiving machine and which leads to the opening between the rolls 214, 215. Fixed in and 25 projecting upwardly from the carrier 217 is a jig pin 218 adapted to fit the jig hole 180 in the outsole. A slide 219 fitting a longitudinal guideway 220 in the carrier 217 is slotted at 221 to permit limited movement of the 30 slide 219 longitudinally of the carrier 217. Fixed upon the slide 219 is a transverse bar 35 or abutment 222. Preparatory to presenting the outsole 172 to the skiving mechanism shown in Fig. 21, its jig hole 180 is slipped 40 over the pin 218 and then the slide 219 is moved longitudinally of the carrier 217 into engagement with the rear end of the outsole and the said end is brought into contact at least at its opposite sides with the bar 222, 45 the outsole turning on the pin 218 if necessary to secure such engagement. In this way, the outsole is exactly positioned upon the carrier 217 which is then moved forward in its guideway in the skiving machine to cause the 50 toe of the outsole to enter between rolls 214, 215 so that when the rolls grip the sole it has been positioned exactly transversely with relation to the matrix in roll 215. Means will also be provided in the machine to insure the 55 correct relation of the sole peripherally of the matrix. After the rolls have thus assumed control of the sole the pin 218 will be withdrawn from the jig hole 180 after which carrier 217 may be moved back from the rolls. 60 As illustrated, the sheet filler 176 is prepared with an edge 223 of predetermined contour and with a notch 224 which may serve to provide a positioning surface or surfaces adjacent to the rear edge of the filler and in 65 predetermined relation to said contour.

This filler may also be skived as indicated in Figs. 23 and 24 to a varying thickness corresponding more or less to the variation in the space between the soles within the inseam of the welted shoe. Thus the thinnest portion 70 of the filler will be in the region, indicated at 226, corresponding to that occupied by the ball portion of the foot in the shoe. A filler of this character forms the subject-matter of a co-pending application filed in the name of 75 Frederick M. Furber, which has now matured as Patent No. 1,582,260, granted April 27, 1926.

The metallic shank stiffener 174 is preferably molded to a vertical shape corresponding 80 to the portion of the outsole against which it is to lie.

The elements of the outsole unit or forepart bottom, thus described, are, according to the preferred manner of practising the invention, assembled and secured in exact predetermined relation in any suitable manner, as, for example, by the aid of an automatic machine of a type which has already been designed for the purpose. So far as the 90 present invention is concerned it is sufficient to state here that preferably suitable adhesive is applied to the outsole over the central portion of the area of its inner surface, as indicated at 240 in Fig. 23. Conveniently the 95 adhesive may be a pitch which is normally hard but may be softened by heat. The shank stiffener 174 while hot is applied to and pressed into the adhesive upon the sole. The adhesive still being maintained soft by heat, the filler 176 is pressed against the adhesive upon the outsole and over the shank stiffener in such a manner that the stiffener becomes embedded in the filler, as shown in Fig. 43. To facilitate the accurate positioning of the 100 filler upon the outsole, the jig hole 180 and the notch 224 may be aligned by fitting them over a jig pin similar to jig pins 148 and 196. Since the outsole, stiffener and filler have been thus firmly secured together in exact 105 predetermined relative position and the filler has had imparted to it a predetermined edge contour and thickness suited to fit the space within the rib 58 of the insole and between the adjacent surfaces of the two soles, the 110 filler is advantageously utilized in positioning the outsole unit correctly upon the welted shoe as will more fully appear. Also, since the toe portion of the upper has been molded, as already explained, to fit the rib of the insole, no distortion of the rib takes place 115 during the lasting operation to be described and little distortion can occur during welt attaching and, therefore, the edge of the filler may be shaped to fit the rib forward of the 120 tip line more closely than rearwardly thereof. Moreover, it is not essential, according to the preferred mode of practising this invention commercially, to make such positioning of the outsole unit on the welted shoe 125 130

mathematically exact because a slight trimming of the outsole and welt will usually be performed after the two have been permanently stitched together. As already mentioned, one of the advantageous characteristics of this invention is that bottom units such as are shown in Fig. 24 may be completed off the manufacturing last and also may be accumulated in quantity ready to be drawn 10 from stock as required to be assembled with other major units for the making of shoes.

Another one of the units of the shoe, herein termed "major units," is the heel which also, as already indicated, is preferably built up 15 and substantially completed before it is assembled with the other units. In the broader aspects of the invention, the heel may be built in various ways but the novel method illustrated in Figs. 25 to 35, inclusive, of the drawings has a number of advantages over prior 20 methods and is claimed as a part of the present invention. The type of heel shown is relatively low and straight, being well suited for a man's shoe. This heel which is designated 25 by the general character 250 is built up of an inner section comprising a rand 252 and a short base lift 254. Next to it is an intermediate section of any desired number of lifts 256, 258 and 260 as shown, for example, in Figs. 25 and 26, while the outer 30 section is the top lift 262. These various elements may be of leather, leather-board or any other suitable material, but it is contemplated that the top lift 262 will be of a good 35 quality of leather and that one or more of the lifts next to it and also the rand 252 will likewise be of leather, while the intermediate lifts may be of a less expensive material. Each lift may be died out in any suitable manner 40 and of a size preferably slightly larger than it is to have in the heel when finished. Indeed, the inner section 252, 254 will preferably be made by an automatic machine which has already been designed for the purpose 45 but so far as the present invention is concerned it may be made in various ways. Not only will the rand 252 be shaped approximately to the periphery of the base lift 254 and secured permanently thereto, as by 50 an adhesive, but the forward edge of the unit will be specially trimmed or otherwise shaped, as shown in Figs. 30 and 35, to fit the rear end of the outsole unit. Thus the forward edge comprises two plane marginal 55 abutting surfaces 264 with a portion 265 of the edge between them cut away to afford sufficient clearance so that when the heel and outsole unit are assembled, as shown in Figs. 46, 47 and 48, the rear end of the latter will 60 fit within the recess or rabbet of the heel thus formed and against the surfaces 264 but will not contact with the surface 265. As shown in Figs. 25 and 35, the lift 256 is gouged or shaped adjacent to its forward end to fit the 65 vertical curvature of the rear end of the

outsole, being thinnest at the center of its forward end and tapering both laterally and rearwardly.

It is contemplated that the several sections of the heel will be assembled, compressed and 70 permanently secured together chiefly by automatic machinery which has already been particularly designed for the purpose, but so far as the invention herein claimed is concerned, such operations may be performed in various 75 ways and with the aid of apparatus of known types. In building the heel as illustrated in Fig. 26, the inner section 252, 254, just referred to, is placed upon a support in the form of a block 266 and then the lifts 256, 258, 260 80 are placed thereon, all being located by any suitable edge gages including a breast gage 267, formed as a ledge on block 266, for the finished surfaces 264, and then while the lifts are held firmly, building nails 268 are driven 85 by drivers 263 through guides 269 and through the lifts so that the collars of the nails rest against or are slightly depressed into the outer surface of lift 260, these nails being located in predetermined relation to 90 each other, to the ledge 267 and to the periphery of the heel blank. It will be noted also, from Fig. 27, that the forward nails used are somewhat shorter than the others because they do not pass through the inner sections 95 252, 254. Thereafter the top lift 262 is spanked on to the projecting ends of the building nails, as shown in Fig. 27, being located laterally by suitable gages or a jig in predetermined relation to the other lifts. 100

Jig holes are then punched in the assembled heel which is subjected at the same time to a preliminary compression as, for example, by apparatus of a character such as is indicated in Figs. 28 and 29 wherein is 105 shown a mold 270 in which the heel is supported on a block 271, the upper surface of which, as in the case of block 266, is complementary to the corresponding face of the heel and is provided with a vertical ledge or shoulder 272 accurately shaped to fit the surfaces 264 of the heel. Normally, the block 271 is held in raised position by a spring 273 engaging a hollow stem 274 projecting downward from the block so that the upper surface of the block lies slightly above the walls of the mold as shown in Fig. 28. The rear wall 275 is shaped to engage the rear curved edge of the heel and the upper edge of the wall is rounded at 276 for a purpose about 110 to be described, but the walls at and adjacent to the breast of the heel need not engage the latter during the pressing and punching operation. Hollow stationary punches 277 are adjustably fixed in the bottom 278 of the 115 mold and serve to form jig holes 279 in the heel, the block 271 having openings fitting over the punches so that the block may slide vertically over them.

When this apparatus is ready for use, the 120

block 271 occupies its highest position with the head of the stem 274 in engagement with the bottom 278 of the mold and with the upper ends of the punches 277 somewhat below 5 the upper face of the block 271. A plunger 280 which is employed to force the heel over the punches 277 occupies its highest position, with sufficient space between it and the walls of the mold to permit the insertion of the 10 heel. With the parts in this position, the heel will be placed upon the block 271 with its surfaces 264 against the shoulder 272. Thereafter the plunger 280 will be brought down upon the top lift and the heel will be forced 15 into the mold cavity, the rounded surface 276 acting to force the surfaces 264 firmly against the shoulder 272. Downward movement of the plunger 280 continues until the block 271 is carried to the bottom of the mold as shown 20 in Fig. 29. The heel having been thus compressed and punched, the block and plunger return to raised position. It will be noted that the jig holes 279 extend only part way through the heel and are unexposed at the 25 tread face of the heel when finished and even after the heel becomes considerably worn. Furthermore, the jig holes are thus located in exact predetermined relation to the surfaces 264, and to the periphery of the heel. 30 This stage in the manufacture of the heel is illustrated in Fig. 30.

The next operation according to the illustrated exemplification of the invention, is slugging which may be performed in any appropriate manner but preferably this slugging is effected with the aid of apparatus such as is indicated in Figs. 31 and 32, wherein the heel is shown supported upon a block 281 having jig pins 282 to enter and fit the jig holes 35 279 and thus locate the heel exactly with respect to the slugging instrumentalities. A die plate 284 containing guide passages 286 for the slugs and located in predetermined lateral relation to the block 281, is brought down on 40 the toplift after which holes for the slugs may be pricked, if desired, by awls guided by said passages. The slugs 288 are then dropped into the passages and driven by drivers 290, as shown in Fig. 32. Thus the slugs 45 are located in exact predetermined relation to each other and to the building nails 268, as well as to the jig holes 279, so that there can be no possible interference between the fastenings, as will be further pointed out.

50 As herein shown, the heel is next trimmed as, for example, by apparatus illustrated diagrammatically in Fig. 33 wherein 292 designates a vertically movable supporting block, the upper surface of which is somewhat inclined and which is provided with jig pins 294 to fit the jig holes 279 in the heel. A plunger 296 is constructed and arranged to engage the upper surface of the heel and, moving down synchronously with the block 55 292, to carry the margin of the heel against a

die or hollow knife 298, the interior surface of which slides over the periphery of the block 292. Thus the heel is first located exactly in predetermined relation to a trimming instrumentality and then while so located the entire edge, including the breast edge, of the heel is trimmed accurately in predetermined relation to the jig holes 279. Also, because of the inclined position of the parts, just referred to, the heel edge has a 70 backward pitch. After the trimming has thus been effected, the plunger 296 is raised and moved away from the heel so that the latter can be removed.

The heel is preferably next presented to a 75 suitable compressing apparatus, such as is illustrated diagrammatically in Fig. 34, wherein 299 designates a supporting block, provided with jig pins 300, similar to but somewhat smaller than the corresponding block 292 just described. Block 299 which forms part of a mold fits within the side wall 301 of the mold, the lower or entrance edge of the wall being rounded as shown at 302. A member 303 forms the remaining wall of the mold cavity into which the heel is forced and in which it is consolidated and compressed under heavy pressure applied through relative approaching movement of the mold members 299, 303. At the beginning of the trimming operation the slugs 288 may project 80 slightly beyond the tread surface of the top lift 262 while the longer building nails 268 will preferably extend substantially just to the inner surface of the rand 252 but as a result of these trimming and compressing operations the thickness of the heel will be 85 slightly reduced, the slugs will be driven substantially flush with the tread surface of the top lift and the points of the building nails will be clinched upon the inner surface of the rand. Likewise under the heavy pressure 90 exerted upon the heel, the material thereof may flow slightly so that as a result of the compressing operation the shape of the heel will be perfected giving substantially its permanent size and shape so that, as already 95 pointed out, the heel before it is applied to the shoe has not only had imparted to it substantially its final shape, as shown in Fig. 35, 100 but also the jig holes 279 are located in exact predetermined relation to the periphery of the heel and to the surfaces 264 so as to ensure a standardized relation between the periphery or edge contour of the heel and the contour 105 of the counter portion of a correspondingly jigged shoe when the heel is assembled on the shoe by the aid of said jig holes and said surfaces 264 and also of other complementary positioning surfaces on the short outsole and the insole, as already described.

110 Thus, as so far described in detail, a relatively few major or principal units are prepared from minor units, or elements, and assembled off the manufacturing last, and if 115

desired they may also be accumulated in quantity, after which such major units, one of each kind, are brought together and permanently secured in the correct desired relation to make a complete shoe. For the purpose of ensuring that the several units shall be assembled in such relation, they are provided with positioning surfaces which may be supplied by jig holes, or other accurately formed surfaces, which preferably are unexposed upon the exterior of the finished shoe and which bear a predetermined and standardized relation not only to the contour or other characteristic of the unit or element on which they are formed but also to similar complementary positioning surfaces on one or more other units or elements of the shoe. Moreover, these positioning surfaces are utilized not only in jigging the units or elements with relation to each other but also in jigging them in standardized relation to instrumentalities for operating thereon by engaging said surfaces with complementary elements of said instrumentalities, such as jig pins, which bear a predetermined relation to the operating means and which also are so located as not to interfere with operations to be performed on the shoe during its manufacture.

According to the particular manner of practising the present method already described and illustrated by way of exemplification of the invention, the major units comprise a molded upper permanently connected to an insole, an outsole unit and a heel, each having approximately the shape that it is to have in the shoe when finished. This procedure constitutes an important characteristic of this invention as compared with ordinary shoemaking methods in which the insole is first applied and secured to the last, then the loose, unmolded upper, in a series of operations, is drawn to the last and secured to the insole after which, in due course, the filling material, the shank stiffener, the outsole and the heel, in sections, are separately applied to the shoe on the last. As has already been suggested, an important advantage of the present method is that many of the shoemaking operations corresponding to operations heretofore performed upon the last are here performed on the shoe parts before they are brought to the last. This result is facilitated by assembling the various minor units or elements into a relatively few major units, as just outlined, before they are finally brought together to make the shoe.

These three major units, which constitute the principal units of a complete shoe, having been thus separately prepared and given approximately the final shape which they are to have in the shoe when finished, they are now ready to be assembled upon the last. Inasmuch, as the heel will preferably be attached by nails driven from the inside of the shoe the heel part of the last will be removed from

the shoe for that operation although the forepart of the last may be allowed to remain in place. For this and other reasons which will shortly appear, the last employed comprises a heel part and a forepart which may be separately inserted and removed from the shoe and which are so constructed and arranged that the total length of the last will progressively increase as the two parts of the last are moved into their normal extended position in the shoe with the result that the upper will be stretched longitudinally as the last is put into place. The particular form of last illustrated in Fig. 36 is well adapted for use in carrying out the present method but its structural features are not claimed in the present application but to a large extent form the subject-matter of a copending application, Serial No. 465,951, filed in the name of Garrett P. S. Cross on May 2, 1921. Briefly, the last 308 comprises a heel part 310 and a forepart 312, which have complementary inclined ends 314, 316 respectively which come into engagement as the heel part is moved along the rear end of the forepart to bring the two parts into longitudinal alignment, after which suitable interlocking devices, indicated generally by the numeral 318, locate the two parts in correct relative position and maintain them in such position. According to the present invention, the bottom of the heel part 310 is provided with a positioning surface which serves different purposes as hereinafter explained and which may be in the form of a jig hole 320 into which a separate pin may be fitted as, for example, when the outsole unit is to be located upon the welted shoe as will shortly appear. However, as illustrated a spring pressed pin 322, forming a permanent element of the heel part, is fitted to slide in said jig hole 320, its outer end being normally pressed into outmost position as shown in Figs. 37 and 40 but being free to be pressed inward flush with the bottom of the last. The heel part 310 also includes the usual thimble hole 324 for a spindle over which the last may be placed when the heel part is to be unlocked from the forepart and removed from the shoe. As indicated in Fig. 37, the margin of the last at its toe and heel ends may be depressed to correspond to and receive the depressed or offset portions 64, 66 of the insole.

In assembling the connected insole and upper shown in Fig. 16 upon the last, the forepart 312 is inserted first and, since the upper will usually be laced as shown in Fig. 37, it is considered preferable to insert the forepart of the last through the bottom of the upper unit by bending back the forepart of the insole. Under some circumstances, however, it may be preferred to insert the forepart of the last, as well as the heel part, through the top of the upper unit. After the forepart of the last has been inserted through the bot-

tom of the unit as described, or before it is inserted if it goes through the top of the unit, the toe of the insole is inserted within the pocket formed at the molded toe of the upper 5 by the inturned flange 140. That portion of the insole between its ends bulges upward, somewhat as indicated in Fig. 36, there being sufficient elasticity in the insole to cause its rib to be pressed into close contact with the 10 upturned margin 142 of the flanged upper at the toe. Under some manufacturing conditions, this interlocking of the insole and upper at the toe, in addition to the firm and permanent connection of these parts at the 15 heel, may be relied upon alone to maintain the proper relative location of the parts until they are further secured together in the side lasting operation. However, a supplemental fastening together of these parts at the toe 20 may be provided as, for example, by two or three light wire staples such as are indicated at 325 which may be inserted through the upper and insole rib by the well-known Good-year upper stapling machine.

25 The heel part 310 of the last is next inserted within the upper unit or "shoe", the rear bottom edge of the last being first pushed down into place at the junction of the upper and the heel reinforce 94, as shown in Fig. 36, and thereafter the forward end of the heel part is forced into the shoe by sliding it along the rear face 314 of the forepart until the locating and locking devices 318 snap into place, thus holding the heel part and forepart 30 in alignment. As the heel part is thus moved from the position shown in Fig. 36 to that shown in Fig. 37 the upper is stretched longitudinally causing the insole to be brought down on the bottom of the last and the spring 35 pressed pin 322 slips up through the forward holes 100 and 68, respectively, in the heel reinforce 94 and insole 54.

40 While for some types of shoes no further lasting may be required except such drawing of the upper to the last as takes place during the welt attaching operation yet according to the preferred manner of practising the method and in order to secure a high quality of work, the sides of the upper between the 45 mold ends should next be lasted. This operation may be performed in any known or suitable manner but in the commercial practice of the present invention, this operation will preferably be performed by a substantially automatic machine such, for example, as one of the general type of that described and claimed in a co-pending application, Serial No. 637,749, filed May 9, 1923 in the name of Robert H. Lawson. In the use of 50 that machine, the two sides of the shoe are lasted simultaneously and, as soon as the upper at each side of the shoe has been drawn to the last, it is immediately secured to the insole by thread. Moreover, the lasting 55 begins upon the two sides of the shoe at points

adjacent to the rear ends of rib 58, which are predetermined as will shortly be explained, and continues automatically until it reaches other predetermined points in the vicinity of the tip line. The latter points are so located that the portion of the upper which is drawn to the last during the lasting operation will merge into or overlap the portion which lies against and already fits the last as the result of the toe molding operation. 75 Throughout the lasting operation, the relative positions of the shoe and of the lasting instrumentalities are controlled entirely by automatically actuated means, as fully set forth in said Lawson application, thus insuring invariably both accuracy and uniformity in the work performed.

So far as the present method is concerned the lasting operation is sufficiently illustrated in Figs. 38, 39 and 40 wherein pincers 326 85 are conventionally shown as operating at opposite sides of the shoe to stretch the upper over the last and against the rib 58 of the insole, after which sewing mechanism indicated by needles 328 permanently secures the 90 upper, while thus stretched, to the insole rib. As shown particularly in Fig. 39 the type of seam employed is a "loop lock" consisting of a sewing thread 330 and an interlooped locking thread 331. This stage in the manufacture 95 of the shoe, after the side lasting has been completed, is illustrated in Fig. 40. According to the usual method of shoe manufacture the lasted shoe is allowed to remain on the last after lasting for perhaps twenty four 100 hours to cause the upper to set but no such delay is necessary in practising the present method not only because of the permanent molding of the ends of the upper but also because the fasteners used in the lasting operation remain permanently in the shoe and are not removed prior to the welt attaching operation as is the common practice.

As illustrated in Fig. 37, the shoe may be brought into the precise longitudinal position 110 desired with relation to the lasting mechanism by engaging the forward side of the pin 322 which projects from the last, with a gage, indicated at 332, which is connected with and bears a predetermined relation to the lasting 115 mechanism. By this method, the shoe is located longitudinally with exactness in desired relation to the mechanisms for operating thereon so that the lasting, including the sewing, begins at predetermined points upon the two sides of the shoe. It is contemplated that the shoe will be located in a similar way with respect to the mechanisms which perform the welt and certain other subsequent operations. This method of relatively locating the shoe and the instrumentalities for operating progressively thereon is not herein claimed but is being made the subject-matter of a separate application, Serial No. 637,039, filed May 7, 1923.

As herein exemplified the next step in the progressive manufacture of the shoe is to attached the welt 334. Preferably the welt, having been grooved and beveled in a preliminary operation as is usual, is then attached to the shoe in any suitable manner by a seam 336 which passes through the welt, the upper and the insole rib at substantially the base of the rib and preferably slightly below the seam 330, 331 formed during the lasting. However, it is contemplated that the welt can advantageously be secured by a substantially automatic machine such, for example, as one of the general type described and claimed in a copending application filed in the names of Laurence E. Topham and Alfred R. Morrill, which has now matured as Patent No. 1,616,714, granted February 8, 1927. The ends of the welt will preferably extend rearwardly slightly beyond the seam 336.

Next the inseam may be trimmed and the welt beaten out flat in any suitable manner. In the commercial use of the present invention, it is contemplated to employ an automatic machine to perform these operations simultaneously, which machine is preferably of the general type of the automatic welt attaching machine just mentioned. Such a machine forms the subject-matter of a copending application filed in the name of the said Morrill, which has now matured as Patent No. 1,689,594, granted October 30, 1928. Fig. 41 illustrates that stage in the manufacture of the shoe when the inseam has been trimmed and the welt beaten somewhat more than half of the way round the shoe.

As shown particularly in Figs. 41 and 46, a filler piece 340 is laid upon the welted shoe approximately to fill the space within the margin of the heel portion of the upper, including the counter, and between the insole and the heel. This filler also extends between the insole and the forepart filler 176, it has a shoulder 341 at or just behind the rear end of said filler and its forward end is tapered toward both the front and the sides so as to give a rounding effect to the outsole in the shank. The filler 340 is provided with a pair of jig holes 342 so spaced and located as to aline 50 with the jig holes 68 in the insole. Before the bottom units are assembled upon the welted shoe, this heel filler 340 is slipped into place over the pin 322 as shown in Fig. 41.

Instead of using a separate filler 340, a member having a similar function in whole or in part may be formed as a portion either of the forepart filler 176 or of the built up heel 250.

Then, the forepart of the shoe bottom, which is the outsole unit shown in Fig. 24, is laid upon the shoe. Preferably a small quantity of adhesive is first spread upon the filler side of the unit to secure it temporarily to the shoe. As this unit is laid by hand, or otherwise, the hole 180 is fitted over the pin 322 and

thus the unit is positioned exactly and with certainty longitudinally of the shoe and its heel end is similarly positioned transversely. Furthermore the periphery 223 of the filler 176 fits within the insole rib 58, more or less closely particularly forward of the tip seam, as already explained. Thus, without any substantial skill or care upon the part of the workman, the entire outsole unit is located accurately in predetermined position upon the shoe. However, if as above stated and as is preferred, the edges of the welt and of the outsole are to be trimmed after the outsole has been permanently attached to the welt, it is unnecessary that the filler should fit against the insole rib with mathematical accuracy either at the toe or at the sides, that is to say, a lateral variation within a limited range will not have any effect upon the accuracy and uniformity of the ultimate product.

With outsole unit temporarily secured by adhesive to the welted shoe these parts are permanently stitched together by a seam 343 in any usual or suitable manner. In Fig. 42, mechanism for performing this operation is indicated, merely conventionally, by a needle 344 and a table or work support 345. While in certain aspects of this invention this stitching may be performed by existing commercial machines, it will preferably be performed on an automatic machine of the general type already mentioned, as, for example, one described and claimed in a copending application filed in the name of the said Laurence E. Topham, which has now matured as Patent No. 1,616,712, granted February 8, 1927.

In this connection it may be here noted that such a standardized shoe as it is an object of the method of the present invention to produce can most advantageously be manufactured commercially and in large quantities with the aid of automatic machines of the type hereinbefore referred to and that, on the other hand, the success of such automatic machines is better assured when the shoes are made generally according to the method herein claimed. Indeed, the method of the present application and the automatic machines herein mentioned have been developed especially for use together in one system.

At this stage in the manufacture of the shoe, or at some later stage if preferred, the upper face of the welt may be wheeled or the stitches separated either by the usual type of machine or by a special machine provided with wheeling or stitch separating mechanism of the usual type, but in which the relative position of such mechanism and the shoe is automatically controlled as the operating point is progressively shifted about the shoe as in the automatic machines hereinbefore mentioned.

Inasmuch as the outsole has been molded to substantially its final shape, as described in

connection with Fig. 19, before it is secured to the shoe, little leveling of the bottom is required. However, as above stated and as shown somewhat exaggerated in Fig. 42, the 5 margin of the outsole is flared outward or away from the upper in the shank as a result of the molding, stitching and other operations thereon and hence it is desirable to 10 press at least this marginal portion of the outsole and of the welt stitched thereto back toward the upper. This operation and any 15 other leveling which may be desired will be performed by any usual or suitable leveling mechanism, such for example as a leveling pad 346 illustrated diagrammatically in Fig. 43.

At this or any other appropriate stage in the carrying out of the method, the edges of the sole and welt may be smoothed or slightly 20 trimmed and set or burnished by the aid of suitable tools or machines such as are customarily employed for the purpose or by automatic machines, of the general type already mentioned, which have already been 25 designed for these purposes, and which are exemplified respectively by copending applications, which have now matured as patents No. 1,616,715 and No. 1,616,717, both granted February 8, 1927, in the name of 30 the said Laurence E. Topham. Preferably, the extreme rear portions of the edges of the outsole and welt will be trimmed or jointed after the heel has been attached.

Preparatory to the heelng operation, if 35 the attaching nails are to be inserted from the inside of the shoe as is preferred, the heel part 310 of the last is removed leaving the forepart 312 in the shoe and then, according to the preferred manner of practising 40 the method, the shoe is presented to a substantially automatic machine which both butts the rear ends of the outsole and welt and also attaches the heel. The preferred method of performing these operations is 45 illustrated, respectively, in Figs. 44 and 46. As shown in these figures and also in Fig. 45, the outsole seam 343 terminates short of the rear end of the outsole but behind the breast edge of the heel. For the butting operation, the shoe, with the heel part 310 of 50 the last removed, is presented, as shown in Fig. 44, to operating instrumentalities which include a pair of sharp-edged plates 348 which are inserted below the ends of the welt 55 so as to turn these ends and the rear end of the outsole upward somewhat away from the insole. These plates serve also as a cutting bed for butting knives 350. For this operation the shoe is supported upon a nail block 60 352 which is shown in Fig. 46 and which is provided with jig pins 354 located and spaced to pass through the jig holes 100 in the heel reinforce 94, the jig holes 68 in the insole 54 and the jig holes 342 in the heel filler 340. The 65 nail block 352 is so connected with the but-

ting instrumentalities already described that the shoe and, therefore, the rear ends of the outsole and welt are presented invariably in predetermined relation to the butting knives 350, the shoe being clamped to the nail block 352 by the plates 348 which are constructed and arranged for movement both vertically and longitudinally of the shoe. With the parts thus positioned, the knives 350 are actuated in a direction normal to the upper 70 surfaces of the plates 348 to trim the welt and the marginal portions of the two sides of the outsole as shown in Fig. 44 and, also, in Fig. 45. Thus two plane finished surfaces 356 are provided on the outsole unit to fit 80 accurately against the corresponding finished surfaces 264 of the heel unit, 250, shown in Fig. 35. Indeed, as illustrated, the heel is assembled on and secured to the shoe while the latter is still supported on the nail block 352 85 and while the rear ends of the outsole and welt still remain somewhat upturned after the removal of the butting plates 348.

Apparatus for attaching the heel, a part of which is illustrated in Fig. 46, includes the nail block 352 having the jig pins 354, above referred to, and also having nail passages 357 for guiding drivers 360. Such apparatus is further disclosed and claimed in a continuing application filed January 30, 1924, Serial No. 689,562. Before the shoe is mounted upon the nail block 352 and jig pins 354 and while the drivers 360 are in lowered position within the nail block 352, a set of attaching nails 362 is deposited, by hand or in any suitable manner, 100 in the nail passages 357 with their heads resting upon the ends of the drivers 360 and with their points extending upwardly. Preferably and as illustrated, these points are specially bent or shaped to cause the nails, when driven into the heel, to follow a curved path extending away from the heel edge thus imparting a considerable holding power to the nails and also preventing the points of the nails, and particularly those nearest the rear 110 of the heel, from penetrating the heel edge. The nail block being thus loaded, the welt and outsole having been butted as already described and the shoe still being positioned upon the nail block 352 by the jig pins 354, the heel 250 is assembled upon the shoe by slipping the jig holes 279 therein over said jig pins 354 and thus the heel is positioned exactly in predetermined relation to the shoe. During the movement of the heel vertically 120 relative to the shoe, the surfaces 264 of the heel come into engagement with the surfaces 356 of the outsole and welt and then through relative movement of a pressure plate 358 and the nail block, the heel will be pressed down firmly upon the shoe the upturned ends of the sole and welt being crowded against the surfaces 264 of the heel by what is in effect a toggle action to produce a close joint at the opposite sides of the shoe, but 125 130

with clearance between, as shown at 359 in Fig. 48.

The heel having been thus exactly located upon the shoe and with the parts under considerable clamping pressure between the nail block 352 and the pressure plate 358, the drivers 360 are actuated to drive the nails 362 through the reinforce 94 and other shoe parts into the heel as already partly described and shown in Fig. 46, the heads of the nails being preferably substantially flush with the surface of the reinforce. Before the shoe is marketed the nails will be covered, as is the common practice, in order to prevent contact of the wearer's heel with the nails, as well as to improve the appearance of the shoe on the inside. It is usual to cement a piece of leather or felt known as a "heel pod", over the nails and that will also serve to cover and conceal the jig holes 68 and 100 in the insole and reinforce.

The relative location of the various fasteners at the heel and of the shoe is shown in the inverted plan view, Fig. 49, from which it will be noted that the attaching nails 362 lie in a line spaced a substantial distance outside of the jig holes 279 and also occupy a definite predetermined relation both to the building nails 268 and to the heel seat lasting tacks 168 and also to the slugs 288 so that none of these fasteners interfere with any of the others. Conveniently, though not necessarily, the building and attaching nails may alternate in approximately the same line around the curved edge of the heel and if desired the building nails may be located directly under the lasting tacks with the slugs in a row outside of all the other fastenings.

So far as the present method is concerned the shoe, after being removed from the apparatus shown in Fig. 46, may be finished in any suitable manner to make it ready for the market, as for example, in part by the aid of an automatic heel finishing machine of the general type disclosed and claimed in two copending applications filed in the name of Alfred B. Fowler, which have now matured as Patents No. 1,630,561 and No. 1,630,564, both granted May 31, 1927. In such a machine, the shoe is mounted upon a work support or jack and presented to a finishing tool and automatic means is provided for relatively moving the work support and tool to cause the edge of the heel to be scoured or otherwise treated from one breast corner to the other. In accordance with the present invention and as illustrated in Fig. 47, the shoe may be located exactly in predetermined relation to the work support, which is designated 367, by providing jig pins 366 therein so located and spaced that they fit the jig holes 100 in the reinforce 94 as well as the other aligned jig holes in the rear portion of the shoe. In Fig. 47, the finishing tool is shown as a scouring wheel 368. For certain of the finishing operations upon

the shoe, the heel part 310 of the last may be reinserted in the shoe, if desired.

The present invention, as thus set forth in detail, has the enormous advantages, among others, that the various shoe parts are standardized and are interchangeable with other similar parts because they are made uniform as to size and shape, both with reference to the chosen standard and with reference to each other; that all of the principal shaping and assembling operations upon the various parts do not require the handling of the entire shoe and last; that a relatively few major shoe units may be produced in large quantities and accumulated as articles of manufacture and then may be drawn from the accumulated stock as required and assembled, upon the last or otherwise, with maximum accuracy and rapidity, the ordinary "guess and try" methods being practically eliminated; that the operations performed upon the last are greatly reduced in number and require practically no skill, care or judgment on the part of the workmen; and that the time intervals between various shoemaking operations may be shortened without sacrifice of quality in the produce.

Moreover, by the practice of the present invention very great economies in the manufacture of shoes are secured, conspicuous among which are a large saving in labor, particularly skilled labor. Also, because of the shortening of the time each shoe remains upon its last, a radical reduction is effected in both the direct and the indirect "last expense", including savings not alone in the lasts themselves but also in shoe racks and in the space required for storage of racks throughout the factory. Again, by way of further example, various shoe parts may initially be cut or formed approximately to final size, thus eliminating considerable waste as compared with existing methods.

Moreover, the standardization of parts and operations and the preparation of uniform units not only result in the production of standardized shoes, that is, shoes all of which nominally of a particular size and shape are, in fact, substantially identical in these and other respects, but also make it practicable to use many automatic machines in which the shoe is wholly supported and guided by mechanical means which are substantial duplicates as employed in successive machines.

Although the complete method hereinbefore described in detail represents the invention as it is now contemplated that it will be practised yet, as already indicated, the invention is not limited in its broader aspects to the inclusion of every step described and, indeed, many of its advantages can be secured by carrying out a portion only of the various steps of the complete method. Accordingly, the appended claims are directed

not only to the method as a whole but also to various steps or combinations of steps and to certain articles of manufacture which may be produced by such method or steps.

5. Therefore, what I claim is:—

1. That improvement in methods of making shoes which consists in providing the heel portion of an upper with jig holes located at opposite sides of the upper and with 10 one or more additional jig holes spaced longitudinally, impaling the upper in said holes to position it in predetermined relation to a form, and then shaping over the form the upper as thus positioned.

15. 2. That improvement in methods of making shoes which consists in providing the heel portion of an upper with three or more positioning surfaces in spaced locations round its end and formed to determine the position of 20 the upper with respect to movement lengthwise of its bottom edge and in the direction of its height, utilizing said surfaces to position the upper in predetermined relation to a form, and then shaping over the form 25 the heel portion of the upper as thus positioned.

3. That improvement in methods of making shoes which comprises providing an upper with one or more positioning surfaces, 30 utilizing said surface or surfaces to determine the position of the upper in predetermined relation to a shaping instrumentality with respect to movement both lengthwise of the bottom edge of the upper and in the direction of the height of the shoe, and then shaping a portion of the upper as thus positioned.

4. That improvement in methods of making shoes which consists in providing the 40 marginal portion of an upper with a plurality of jig holes in predetermined relation to a selected characteristic of the upper, engaging the upper in said jig holes and thereby fixing the upper relatively to a form, and then shaping over the form the upper as thus positioned.

5. That improvement in methods of making shoes which consists in providing a shoe part with one or more jig holes, engaging the 50 shoe part in said hole or holes in positioning said part in predetermined relation to a molding instrumentality, and molding said part as thus positioned.

6. That improvement in methods of making shoes which consists in providing a portion of a shoe part which is not visible in the finished shoe with one or more positioning surfaces formed to determine the position of 60 said part with respect to movement in different directions, utilizing said surface or surfaces in positioning said part in predetermined relation to a shaping instrumentality, and shaping said part by pressure as thus positioned.

65. 7. That improvement in methods of mak-

ing shoes which consists in providing a shoe part with one or more jig holes, engaging the shoe part in said hole or holes by one or more jig pins in positioning said part in predetermined relation to a molding instrumentality, 70 molding said part as thus positioned and removing the pin or pins before the molding operation is completed.

8. That improvement in methods of making shoes which consists in providing an end portion of an upper with at least three jig holes and utilizing said holes in jiggling the upper to position it around a form having a shape corresponding approximately to the final shape of a portion of the upper, and then 80 shaping over the form the upper as thus positioned.

9. That improvement in methods of making shoes which consists in jiggling an end portion of an upper by utilizing one or more 85 positioning surfaces in the marginal portion of the upper in positioning the upper relatively to a form and with respect to movement in different directions, and molding the upper as thus positioned over the form. 90

10. That improvement in methods of making shoes which consists in providing an upper with positioning surfaces in predetermined relation to selected points of the upper, then utilizing said surfaces in jiggling the 95 upper with relation to a form to prevent, independently of the skill of the operator, any shifting of the upper affecting the accuracy of the shape to be imparted to the upper, and molding the upper, as thus positioned, over 100 the form.

11. That improvement in methods of making shoes which consists in jiggling an end portion of an upper by utilizing one or more 105 positioning surfaces thereon to position the upper with relation to a form and with respect to lengthwise, lateral and angular movements, and molding the upper, as thus positioned, over the form.

12. That improvement in methods of making shoes which consists in providing the toe 110 of an upper with a plurality of jig holes formed in the margin of the upper in predetermined relation to a characteristic of the upper, engaging the upper in said jig holes to 115 position it in predetermined relation to a molding instrumentality, and molding the toe of the upper as thus positioned.

13. That improvement in methods of making shoes which consists in providing the 120 marginal portion of the toe of an upper at each of its opposite sides with a positioning surface formed to determine the location of the upper with respect to movement in different directions, utilizing said surfaces to 125 position the upper in predetermined relation to a form; and then shaping the upper as thus positioned over the form.

14. That improvement in methods of making shoes which consists in providing the 130

- margin of the toe of an upper with one or more positioning surfaces, utilizing said surface or surfaces in positioning the outspread upper in predetermined relation to a shaping instrumentality with respect to movement in all directions in the plane of the upper, and then shaping a portion of the upper as thus positioned. 70
15. That improvement in methods of making shoes which consists in jiggling the toe of an upper relatively to a form, and molding the toe of the jiggled upper over the form to produce an inturned flange and an upstanding margin. 75
15. 16. That improvement in methods of making shoes which comprises gripping and shaping the toe of an upper off the last and producing an upstanding margin thereon and while the upper is gripped by the shaping instrumentalities trimming surplus material from said margin. 80
25. 17. That improvement in methods of making shoes which consists in molding an end portion of an upper off the last and while the upper is subjected to molding pressure trimming off its margin around said end portion. 85
30. 18. That improvement in methods of making shoes which comprises gripping and shaping the toe of an upper off the last and while the upper is gripped by the shaping instrumentalities trimming surplus material from its margin by a cut substantially perpendicular to the face of the upper along the line of cut. 90
35. 19. That improvement in methods of making shoes which consists in providing two parts of an upper each with one or more positioning surfaces, securing said parts together in relative positions controlled by the use of 100 said positioning surfaces, and at a different stage in the preparation of the upper utilizing a positioning surface or surfaces on at least one of said parts to fix them in a predetermined relation to an operating instrumentality and employing said operating instrumentality to perform a shaping operation on the part as thus positioned. 105
50. 20. That improvement in methods of making shoes which consists in providing the tip and the vamp of an upper each with one or more positioning surfaces, securing said tip and vamp together in relative positions controlled by the use of said positioning surfaces, and thereafter utilizing the same positioning surfaces for positioning the toe of the upper in predetermined relation to a toe form and shaping over the form the upper as thus positioned. 110
55. 21. That improvement in methods of making shoes which consists in providing the tip and the vamp of an upper each with jig holes at opposite sides of said parts, impaling the tip and vamp in said jig holes and alining corresponding holes so as to fix the relative 115 positions of the tip and vamp, stitching the tip and vamp together in the relative positions thus fixed, and utilizing the same jig holes to determine the position of the united tip and vamp in predetermined relation to a form, and then shaping over the form a part 70 of the tip and vamp as thus positioned. 120
22. That improvement in methods of making shoes which consists in providing the opposite sides of an upper each with one or more positioning surfaces, securing the rear ends of the opposite side portions of the upper together in a relation determined by utilizing said surfaces, utilizing the same surfaces to position the upper in predetermined relation to a form, and shaping the upper 80 over the form. 125
23. That improvement in methods of making shoes which consists in providing a positioning surface at each side of the toe portion of an upper, providing one or more positioning surfaces at each side of the heel portion of the upper, securing the opposite sides of the upper at the heel end in a relation determined by utilizing a plurality of said surfaces, utilizing some of the same surfaces to determine the position of the upper with relation to an upper shaping instrumentality, and shaping the upper as thus positioned. 90
24. That improvement in methods of 95 making shoes which consists in dieing out a portion of an upper and simultaneously providing the opposite sides of its marginal portion each with an inwardly extending slit adjacent to the point at which the inseam is to begin or end and thereafter molding inwardly the marginal portion of the upper in the rear of said slits while leaving extending upward that portion of the margin of the upper immediately forward of the slits. 100
25. That improvement in methods of preparing insoles which consists in forming on an insole blank in predetermined relation to each other an upper-attaching rib and one or more positioning surfaces within the insole 105 margin adapted to be utilized in positioning the insole for a subsequent manufacturing operation. 110
26. That improvement in methods of preparing insoles which consists in shaping an 115 insole blank to a predetermined contour and providing said blank with an upper-attaching rib in predetermined relation to its contour, and further providing the insole with one or more jig holes in predetermined relation to said rib and contour and adapted to be utilized in positioning the insole for a subsequent manufacturing operation. 120
27. That improvement in methods of preparing insoles which consists in forming an 125 upper-attaching rib on an insole blank, and trimming said blank and providing it with a jig hole by utilizing the rib as a positioning member to determine the final contour of the insole in predetermined relation to the contour 130

- of the rib and to determine the location of the jig hole.
28. That improvement in methods of preparing insoles which consists in forming an insole with an upper-attaching rib, utilizing said rib to determine the position of the insole in relation to one or more punching instrumentalities, and punching one or more jig holes in the insole as thus positioned.
- 10 29. That improvement in methods of preparing parts of shoes which consists in molding a shoe part, trimming said part to a predetermined contour and punching one or more jig holes in said part so as to locate said hole or holes and said contour in predetermined relation.
- 20 30. That improvement in methods of preparing parts of shoes which consists in forming an insole with an upper-attaching rib, utilizing said rib as a positioning member to determine the position of the insole in relation to a cutter, and trimming the insole as thus positioned to a contour in predetermined relation to the contour of the rib.
- 25 31. That improvement in methods of preparing parts of shoes which consists in shaping an insole reinforcing piece substantially to the curvature and edge contour of the bottom face of the heel portion of a last, and providing said piece with one or more jig holes in predetermined relation to its contour and adapted to be utilized in positioning said piece in assembled relation to an insole.
- 35 32. That improvement in methods of preparing parts of shoes which consists in providing a flat, insole-reinforcing plate of moldable material but having some elasticity, subjecting the plate to molding pressure so as to impart to it a curvature in excess of that desired in the finished shoe and, while the plate is under molding pressure, trimming its edge at a bevel and forming positioning surfaces within its margin in predetermined relation to the trimmed edge of the plate, and then releasing the plate from pressure to permit it partially to flatten out.
- 40 33. That improvement in methods of making soles which consists in providing an outsole with one or more positioning surfaces in predetermined relation to its contour and at least one of which is formed by a jig hole within said contour, and subsequently utilizing said surface or surfaces to position the outsole in relation to an instrumentality for performing a further shaping operation upon it prior to its attachment to the shoe.
- 45 34. That improvement in methods of making soles which consists in providing a short outsole with one or more positioning surfaces at its rear end and subsequently utilizing said surface or surfaces to position the outsole in relation to an instrumentality for performing a further manufacturing operation upon it prior to its attachment to the shoe.
- 50 35. That improvement in methods of making soles which consists in providing a short outsole with a rear end having a plane surface or surfaces adjacent to the opposite sides of the outsole and then positioning the outsole in relation to an instrumentality for performing a further manufacturing operation upon it by bringing said surface or surfaces into engagement with a complementary abutment.
- 55 36. That improvement in methods of making soles which comprises providing a sole blank with a jig hole and with a plane surface and then utilizing said hole and surface to position the sole in relation to an instrumentality for performing a further manufacturing operation upon it.
- 60 37. That improvement in methods of making soles which consists in providing a short outsole with a jig hole and with a substantially straight rear end and then positioning said outsole upon a support for a further manufacturing operation by engaging said hole with a jig pin on said support and by bringing said end at opposite sides of the sole into contact with a complementary abutment carried by said support.
- 65 38. That improvement in methods of preparing soles which consists in providing an outsole with a jig hole in a permanent part thereof unexposed in the finished shoe, utilizing said jig hole in positioning the outsole in relation to a molding instrumentality, and molding the outsole as thus positioned.
- 70 39. That improvement in methods of preparing soles which consists in providing an outsole with a jig hole, utilizing said jig hole in positioning the outsole in relation to a skiving instrumentality and then skiving in the shank the opposite edges of the outsole as thus positioned.
- 75 40. That improvement in methods of preparing soles which consists in skiving the rear portion of a short outsole to a predetermined thickness and as a part of the same operation reducing the marginal thickness of the outsole in the shank.
- 80 41. That improvement in methods of preparing soles which consists in molding an outsole while in temper to substantially the longitudinal and transverse curvatures desired for the finished shoe, allowing the outsole to dry, pressing the marginal portion only of the outsole into one plane and then trimming it while so pressed.
- 85 42. That improvement in methods of preparing soles which consists in molding an outsole to substantially the shape desired for the finished shoe, clamping the molded outsole in predetermined relation to a member having an edge contour corresponding substantially to the desired edge contour of the finished sole, and then trimming the molded outsole to said contour.
- 90 43. That improvement in methods of

- making shoes which consists in giving an outsole a predetermined contour and providing it with a jig hole in its rear portion, forming a filler piece substantially complementary to the contour of the rib of an insole, providing said filler piece with one or more positioning surfaces, and utilizing said jig hole and said surface or surfaces in securing said outsole and filler piece together in a predetermined relation. 5
44. That improvement in methods of making heels which consists in preparing a plurality of heel lifts including a comparatively short base lift, securing a rand to said base lift, assembling said lifts and securing them together and forming in said lifts one or more jig holes, all prior to attachment of the heel to a shoe. 10
45. That improvement in methods of making heels which consists in assembling a base lift with one or more other heel elements, and forming in said assembled parts one or more jig holes extending from the heel seat face of the base lift a distance less than the height of the finished heel and adapted to be utilized in positioning the heel in predetermined relation to a shoe. 15
46. That improvement in methods of making heels which consists in assembling and securing together a plurality of lifts including a comparatively short base lift, and forming in said assembled lifts a plurality of jig holes, including a hole in front of said short base lift adapted to be utilized in positioning the heel in relation to a short outsole. 20
47. That improvement in methods of making heels which consists in assembling and securing together a plurality of lifts, forming in the parts thus assembled a plurality of jig holes located in or near the longitudinal median line of the heel and spaced lengthwise of the heel and adapted to be utilized in positioning the heel on a shoe and imparting to the heel prior to such positioning substantially the shape desired in the finished shoe with the heel edge and said hole or holes in predetermined relation. 25
48. That improvement in methods of making heels which consists in forming one or more jig holes in a heel, and temporarily inserting a pin or pins in said hole or holes for positioning said heel in relation to an instrumentality for performing a further manufacturing operation upon the heel prior to its attachment to a shoe. 30
49. That improvement in methods of making heels which consists in assembling and securing together a plurality of lifts, forming one or more jig holes in the heel thus assembled, utilizing said hole or holes to position the heel in relation to a die, and then dying out the heel as thus positioned. 35
50. That improvement in methods of making heels which consists in providing a heel having one or more jig holes in predetermined relation to its edge contour, and then compressing the heel symmetrically with respect to said hole or holes to preserve the relation between the hole or holes and said contour. 40
51. That improvement in methods of making heels which consists in assembling and securing together a plurality of lifts including a comparatively short base lift, forming one or more positioning surfaces on said base lift and utilizing said surface or surfaces in positioning the heel in relation to an instrumentality for performing a further manufacturing operation upon it prior to its attachment to the shoe. 45
52. That improvement in methods of making shoes which consists in forming one or more positioning surfaces on a heel blank, utilizing said surface or surfaces in positioning the blank in relation to means for performing a manufacturing operation thereon, and thereafter utilizing the same surface or surfaces in positioning the heel in correct relation to a shoe. 50
53. That improvement in methods of making shoes which consists in assembling an upper and an insole in a relation to each other determined by utilizing one or more positioning surfaces formed on each of said parts, and then molding the upper over the insole and securing said parts together in the relation thus determined. 55
54. That improvement in methods of making shoes which consists in assembling an upper and an insole by utilizing one or more jig holes formed in one of said parts to determine its relation to the other part, and then shaping the upper over the insole and securing it to the insole. 60
55. That improvement in methods of making shoes which consists in assembling an upper and an insole in a relation determined by utilizing one or more jig holes formed in an end portion of each of said parts, and then inserting fastenings to secure said parts together in the relation thus determined. 65
56. That improvement in methods of making shoes which consists in positioning an upper in predetermined relation to a form and to an insole by utilizing pins temporarily inserted in jig holes formed in the upper, shaping the upper over the form and securing it to the insole in the relation thus determined. 70
57. That improvement in methods of making shoes which consists in jiggling an upper and an insole relatively to a form, shaping the upper over the form, and securing it to the insole. 75
58. That improvement in methods of making shoes which consists in positioning an end of an upper relatively to a form and to an insole by utilizing jig holes formed in the opposite sides of the upper, and then shaping 80

the upper over the form and the insole and securing it to the insole.

59. That improvement in methods of making shoes which consists in providing an upper and an insole at the heel portion each with a plurality of jig holes, assembling the upper and the insole in a relation to each other, and to a form determined by impaling the parts in said jig holes, molding the heel 10 portion of the upper over the form and insole and securing it to the insole.

60. That improvement in methods of making shoes which consists in fixing the heel portion of an insole in predetermined 15 relation to a support with respect to lengthwise and lateral swinging movement of the insole by utilizing a plurality of jig holes previously formed in said heel portion in predetermined relation to a contour of the insole.

20 61. That improvement in methods of making shoes which consists in providing an insole with a plurality of positioning surfaces within its margin, engaging said surfaces by complemental positioning elements 25 associated with operating mechanism, and performing an operation upon a part of the shoe while the insole is maintained in such position.

30 62. That improvement in methods of making shoes which consists in jiggling one end of an insole on a form by engaging one or more positioning surfaces formed on said insole by a member or members having a predetermined relation to said form, similarly jiggling 35 an upper in relation to said form, shaping the upper to the form, and securing it to the insole.

40 63. That improvement in methods of making shoes which consists in fixing an insole in predetermined relation to a form by projecting a plurality of pins carried by the form through jig holes previously formed in an end portion of the insole, shaping the corresponding end portion of the upper over the 45 form and insole, and securing it to the insole.

64. That improvement in methods of making shoes which consists in assembling the heel ends of an upper and an insole with relation to a form by utilizing a plurality of 50 positioning surfaces on each of said parts to control the relation of the heel ends of the insole and upper to each other and to the form and to point the toe end of the insole in predetermined relation to the toe end of the upper, and then shaping the heel portion of 55 the upper over the form and insole and securing it to the insole.

65. That improvement in methods of making shoes which consists in forming inwardly extending slits in the marginal portions of both an upper and a counter adjacent to the points at which the inseam is to begin and end, forming inturned flanges on both the upper and the counter in the rear of said slits

and then assembling and securing together 65 said upper, said counter and a ribbed insole.

66. That improvement in methods of making shoes which consists in assembling an upper and a molded end stiffener having an in-turned flange and positioning an end portion 70 of the upper and said stiffener in a relation, with respect to movement round said end, determined by utilizing a plurality of positioning surfaces previously formed on the upper and stiffener and securing the upper to 75 the stiffener in the relation thus determined.

67. That improvement in methods of making shoes which consists in assembling over a form an upper and a previously molded end stiffener and positioning an end portion of the 80 upper in a relation to the form determined by utilizing a plurality of positioning surfaces previously formed on the upper, molding the end portion of the upper about the stiffener and the form, and securing the upper to the stiffener while they are in the relation to each other thus determined.

68. That improvement in methods of making shoes which consists in molding a counter substantially to the shape which it is to 90 have in the finished shoe, assembling said molded counter and an upper over a form, forming the heel portion of the upper over the counter and form, and thereafter mounting said molded counter and upper on a last 95 and performing subsequent manufacturing operations on the shoe.

69. That improvement in methods of making shoes which consists in molding the toe of an upper to interlock with an upper-attaching rib and a feather of an insole to locate the toe of the insole and the upper in predetermined relation to each other, molding the heel portion of the upper over the insole and securing the heel portion of the upper while 100 under molding pressure to the insole, and thereafter inserting the toe of the insole in the toe of the upper in said relation.

70. That improvement in methods of making shoes which consists in assembling over a 110 form the heel portion of an upper and an insole together with an insole reinforcing member, shaping the upper over the form and insole, and securing it to the insole by fasteners extending through said reinforcing member.

71. That improvement in methods of making shoes which consists in assembling over a form the heel portion of an upper and an insole together with an insole reinforcing member of substantially harder material than the insole and positioned between the insole and the form, and then shaping the upper over the form and securing it to the insole by fasteners clinched in said reinforcing member.

72. That improvement in methods of making shoes which consists in providing a last, an upper, and a sole each with one or more

- positioning surfaces, and building the shoe by utilizing said positioning surfaces to control the relations in which said shoe parts are assembled and secured together. 65
- 5 73. That improvement in methods of making shoes which consists in molding the toe end of an upper and forming an inturned flange on the upper, securing the upper at its ends to the ends of an insole, inserting a last 10 in the shoe and stretching the upper by means of the last while the intermediate portions of the upper and insole are unconnected. 70
- 10 74. That improvement in methods of making shoes which consists in permanently securing an upper round one end to the corresponding portion of an insole, molding the upper adjacent to the other end with an inturned flange, and thereafter inserting a last 15 in the shoe and stretching the upper by forcing the last against said other end of the upper. 75
- 15 75. That improvement in methods of making shoes which consists in shaping the heel portion of an upper and securing it permanently to an insole at opposite sides of the heel seat, molding the toe of the upper with an inturned flange, inserting a collapsed last 20 in the shoe, and stretching the upper by expanding the last. 80
- 20 76. That improvement in methods of making shoes which consists in jigging an insole in a predetermined relation to a form, shaping an upper over the form, securing the upper to the insole at opposite ends only 25 thereof, and thereafter inserting a last in the shoe and stretching the upper about the last. 85
- 25 77. That improvement in methods of making shoes which consists in providing an upper and an insole each with one or more 30 positioning surfaces including a jig hole and jigging the upper on the insole by utilizing said surfaces to control the relative positions in which said parts are assembled, securing said parts together in the relation thus determined, and thereafter inserting a last in the upper and stretching the upper about the last. 90
- 30 78. That improvement in methods of making shoes which consists in assembling together an upper and an insole in a relation 35 controlled by utilizing one or more positioning surfaces on one of said parts in positioning it upon the other part with respect to movement in different directions, stretching the upper over a last, and securing the upper 40 and the insole together. 95
- 35 79. That improvement in methods of making shoes which consists in providing one end portion of an upper and an insole each with one or more positioning surfaces in predetermined relation to selected characteristics of said parts, utilizing said positioning surfaces 45 in relatively positioning said end portions of the upper and insole and securing said parts together in the relation thus determined, 100
- 40 molding the other end portion of the upper, and thereafter inserting a collapsed last in the shoe and expanding said last to stretch the upper between its opposite ends. 105
- 45 80. That improvement in methods of making shoes which consists in permanently securing an upper round one end to the corresponding portion of an insole, molding the upper adjacent to the other end with an inturned flange, inserting the free end of the insole in the molded upper and against said flange and thereafter inserting a last in the shoe and stretching the upper by forcing the last against said other end of the upper. 110
- 50 81. That improvement in methods of making shoes which consists in molding the toe 55 of an upper and forming an inturned flange, shaping the heel portion of the upper over an insole and securing permanently to the insole the inturned flange thus formed on said heel portion, bending the toe end of the insole away from the upper and, while the upper is laced, inserting the forepart of a two-part collapsible last through the opening between the free ends of the upper and insole, locating the toe of the insole in engagement with the inturned flange at the toe of the upper and securing the parts together at the toe in such relation, thereafter inserting the heel part of the last through the top of the upper and stretching the upper by forcing said heel part against the heel part of the upper, and then further securing the upper and insole together while on the last. 90
- 55 82. That improvement in methods of making shoes which consists in securing an upper 60 to a sole at one end of each, inserting one part of a divided last through the bottom of the upper while the lower portions of the top of the upper at opposite sides of the slit are held against spreading beyond normal relation, 65 locating the free ends of the upper and sole in normal relation, inserting another part of the last through the top of the upper against the first mentioned part of the last and further securing the upper and sole together. 100
- 60 83. That improvement in methods of making shoes which consists in securing an upper and a sole together at one end of each, inserting one part of a divided last within the upper, fitting the unsecured ends of the upper 70 and sole together, thereafter inserting another part of the last within the upper and against the first mentioned part of the last and further securing the upper and sole together. 105
- 65 84. That improvement in methods of making shoes which consists in providing an upper and an insole each with one or more positioning surfaces in predetermined relation to a contour thereof, securing the upper to the insole in a relation determined by utilizing said surface or surfaces, and thereafter securing an outsole to the shoe in a relation 75
- 70 110
- 75 115
- 80 120
- 85 125

- determined by utilizing such a surface or surfaces on the insole and one or more positioning surfaces formed on the outsole.
85. That improvement in methods of making shoes which consists in positioning an insole in a relation to a form determined by utilizing a jig hole formed in the insole, shaping an upper over the form and securing it to the insole thus positioned, mounting said shoe 10 parts on a last, and thereafter positioning an outsole in a relation thereto determined by utilizing said jig hole in the insole and a jig hole previously formed in the outsole and securing the outsole to the shoe.
86. That improvement in methods of making shoes which consists in positioning an outsole on a shoe in a location determined by utilizing a jig hole formed in the rear portion of the outsole and one or more additional 20 positioning surfaces located at the inner face of the outsole and invisible from the outer face of the outsole, and thereafter securing the outsole to the shoe by a line of fastenings extending round the outsole.
87. That improvement in methods of making welt shoes which consists in securing an upper and a welt to the rib of an insole, positioning an outsole on the shoe mounted on a last in a location determined by utilizing a 30 positioning surface on the last, a complementary positioning surface in the rear portion of the outsole and one or more additional positioning surfaces on the outside engaging the rib of the insole, and securing the outsole to the shoe in the position thus determined.
88. That improvement in methods of making shoes which consists in providing an insole with a rib of predetermined contour and a jig hole, providing an outsole with a jig hole 40 and securing to the outsole in predetermined relation to its edge contour a filler piece having an edge contour substantially complementary to the rib, assembling said insole and outsole with an upper upon a last by alining said jig holes in the insole and outsole with a positioning surface on the last and by engaging said filler piece with the rib of the insole, and securing the said shoe parts in the relations thus determined.
89. That improvement in methods of making shoes which consists in forming one or more positioning surfaces on an outsole, utilizing said surface or surfaces in positioning the outsole with relation to means for 50 forming a shaping operation on the outsole, and thereafter utilizing the same surface or surfaces in positioning the outsole in correct relation to a shoe.
90. That improvement in methods of making shoes which consists in securing a portion of the margin of an upper to the face of the heel portion of an insole, providing a filler piece tapering toward its forward end and shaped to lie within the space between the 60 edges of the secured portion of the upper, 65 then placing said filler piece in such space, laying an outsole over the tapering end of the filler piece and then attaching a heel to the shoe over the filler piece.
91. That improvement in methods of making shoes which comprises providing an insole, an outsole and a filler piece each with at least one jig hole and then assembling and securing together said parts with an upper in a relation determined by such jig holes. 70
92. That improvement in methods of making shoes which consists in providing a partially completed shoe having a short outsole with a jig hole therein, forming an unattached heel with a rabbet, with one or more 80 surfaces to abut against the rear end of the outsole and with one or more other positioning surfaces including a surface provided by a jig hole within the margin of the heel, positioning the heel in predetermined relation 85 on the shoe by alining said jig holes, and securing the heel to the shoe, as thus positioned, by a line of fastenings inserted round the margin of the heel in locations spaced from 90 said positioning surfaces.
93. That improvement in methods of making shoes which consists in providing a partially completed shoe with a short outsole having a jig hole adjacent to its rear end, providing an unattached heel with a rabbet 95 and with a jig hole in its rabbeted portion, positioning said heel on said shoe by abutting its rabbeted portion against the end of the outsole and temporarily inserting a pin 100 in the jig hole in the outsole and the jig hole in the heel, and thereafter permanently securing the heel to the shoe and removing said pin.
94. That improvement in methods of making shoes which consists in providing a partially completed shoe having one or more 105 positioning surfaces on its heel portion, providing an unattached heel with one or more complementary positioning surfaces, assembling said shoe and heel in a relation to each other and to a nail driving instrumentality 110 determined by utilizing said positioning surfaces on the shoe and heel, and driving nails to secure the heel to the shoe as thus positioned. 115
95. That improvement in methods of making shoes which consists in providing in an unattached heel a jig hole in predetermined relation to the contour of the heel, positioning said heel in relation to a partially completed shoe by utilizing a pin temporarily inserted in said jig hole, securing the heel to the shoe, and removing the pin. 120
96. That improvement in methods of making shoes which consists in assembling a partially completed shoe and an unattached heel each provided with one or more jig holes which in the heel terminate short of its outer 125

face, positioning said shoe and heel in predetermined relation by inserting a pin in corresponding holes in the shoe and heel from the inside of the shoe, and driving heel-attaching 5 nails from the inside of the shoe to secure the heel to the shoe.

97. That improvement in methods of making shoes which consists in providing a partially completed shoe and an unattached heel 10 each with one or more positioning surfaces, mounting the shoe on a support carrying one or more complemental positioning members and bringing said positioning members into predetermined relation to said positioning 15 surfaces to locate the heel relatively to the shoe on the support, and permanently securing the heel to the shoe as thus located.

98. That improvement in methods of making shoes which consists in assembling an un- 20 attached heel and a partially completed shoe including a sole having at its heel portion a reinforcing piece of substantially harder material than the sole, and attaching the heel to the shoe by driving nails from within the 25 shoe through said reinforcing piece into the heel.

99. That improvement in methods of making shoes which consists in assembling an un- 30 attached heel with an upper, an insole, an out- sole and an insole-reinforcing member of sub- stantially harder material than the insole, and permanently attaching the heel by fastenings inserted through said reinforcing member.

35 100. That improvement in methods of making shoes which consists in assembling an unattached heel with an upper, an insole, a short insole and an insole-reinforcing member, and permanently attaching the heel by a 40 series of nails inserted through said insole and said reinforcing member.

101. That improvement in the art of making 45 shoes which comprises providing a heel with one or more positioning surfaces, utilizing said surface or surfaces to position the heel successively in predetermined relation to (1) an instrumentality for trimming the heel edge and (2) a partially completed shoe, and then permanently securing the heel to the shoe 50 while thus positioned thereon.

102. That improvement in methods of making 55 shoes which consists in providing a heel with one or more positioning surfaces, and utilizing said surface or surfaces to position the heel successively in different predetermined relations to different fastening inserting instrumentalities to prevent interference between the fastenings inserted by the several said instrumentalities.

60 103. That improvement in methods of making 65 shoes which consists in providing an un- attached heel with one or more positioning surfaces at predetermined points unexposed in the finished shoe and utilizing said surface or surfaces to position the heel in standard-

ized relation to mechanism for operating thereon.

104. That improvement in methods of making 70 shoes which consists in providing an un- attached heel with a plurality of jig holes and applying said heel to a work support provided with a plurality of jig pins constructed and arranged to engage corresponding jig holes in the heel and thereby locating the heel in standardized relation to mechanism for 75 operating thereon.

105. That improvement in methods of making 80 shoes which consists in providing the heel portion of an insole with one or more positioning surfaces, utilizing said surface or 85 surfaces to position the insole in predetermined relation to fastening inserting instrumentalities for securing the upper to the insole, providing an unattached heel with one or more corresponding positioning surfaces, and utilizing said surfaces on the insole and the heel to position said parts in predetermined relation to instrumentalities for driving heel-attaching nails in different locations 90 from the upper-securing fastenings.

106. That improvement in methods of making 95 shoes which consists in securing an upper and a welt to an insole and providing the rear portion of the insole with one or more positioning surfaces adapted to be utilized to determine the position of the insole with respect to lengthwise and lateral movement, utilizing said surface or surfaces to position the shoe in predetermined relation to means for butting the rear ends of the welt, 100 and butting said ends with the shoe thus positioned.

107. That improvement in methods of making 105 shoes which consists in securing an upper and a welt to an insole, securing a short outsole to the welt, and utilizing one or more positioning surfaces on the shoe to position it in predetermined relation to instrumentalities for butting the rear ends of the 110 welt and outsole.

108. That improvement in methods of making 115 shoes which consists in providing a rabbeted heel with a jig hole in predetermined relation to the marginal portions of the shoulder of the rabbet and providing a short outsole with a jig hole in predetermined relation to the marginal portions of its rear end, utilizing said jig holes in positioning the heel upon the outsole with said rear end lying within said rabbet, and then securing the 120 heel to the shoe by a plurality of nails.

109. That improvement in methods of making 125 shoes which consists in providing a short outsole and a rabbeted heel, securing a welt to an upper and insole, securing the short outsole to said welt, butting the rear ends of the welt and outsole to fit corresponding surfaces on said heel, upturning such butted portions, engaging the heel with said upturned portions and forcing it into position on the 130

heel seat while bending back said upturned portions to insure a close joint, and then securing the heel to the shoe.

110. That improvement in methods of 5 making shoes which consists in skiving the rear portion of a short outsole to a predetermined thickness, providing a heel with a rabbet of a depth corresponding to the skived portion of the outsole, laying said outsole and 10 said heel on a shoe with the end of the outsole fitting said rabbet and then securing the outsole and heel to the shoe.

111. That improvement in methods of 15 making shoes which consists in securing a welt to an upper and an insole, securing a short outsole to said welt, butting the rear ends of the welt and outsole, providing a rabbeted heel including a short base lift and a rand and shaping the forward ends of said 20 lift and rand to fit the butted ends of the welt and outsole, placing said fitted surfaces together and securing the heel to the shoe.

112. That improvement in methods of 25 making shoes which consists in providing the heel portion of a shoe including a heel with one or more jig holes extending from the inside of the shoe but stopping short of the tread face of the heel and then utilizing said 30 jig holes to position the shoe in relation to an instrumentality for operating upon the heel.

113. That improvement in methods of 35 making shoes which consists in providing a plurality of shoe units, comprising an upper and a plurality of bottom units, each independently of the others with one or more positioning surfaces formed and arranged to bear a predetermined relation to a surface or surfaces formed on another of said units, utilizing 40 such surfaces on the upper and bottom units to control the relative positions of the units in assembling them in the shoe, and securing the units together.

114. That improvement in methods of 45 making shoes which consists in providing a plurality of shoe units comprising an upper and one or more bottom units each with one or more positioning surfaces formed and arranged to bear a predetermined relation to 50 a surface or surfaces on one of the other units, working the upper into conformity to the contour of a shoe form in a relation to the form determined by utilizing said surface or surfaces on the upper, assembling said units 55 in relations determined by utilizing said surfaces thereon, and thereafter permanently securing the units in such relations.

115. That improvement in methods of 60 making shoes which consists in providing a plurality of shoe parts each with one or more positioning surfaces formed and arranged to bear a predetermined relation to a surface or surfaces on another of said parts, utilizing one or more such surfaces on one of said parts 65 to position said part in predetermined rela-

tion to a molding instrumentality, molding said part as thus positioned, assembling said parts in relations predetermined by utilizing such surfaces on different parts, and permanently securing the parts in such relations.

116. That improvement in methods of 70 making shoes which consists in providing a plurality of shoe units comprising an upper and one or more bottom units each with one or more positioning surfaces formed and arranged to bear a predetermined relation to a surface or surfaces on one of the other units, utilizing said surfaces in assembling the units to control the relation of said units, and thereafter securing the units in the relations thus 75 determined by inserting fastenings spaced from said positioning surfaces.

117. That improvement in methods of 80 making shoes which consists in providing a plurality of shoe units each with one or more 85 positioning surfaces formed and arranged to bear a predetermined relation to a positioning surface on another unit, utilizing the positioning surfaces on two or more of said units to control the assembling of said units, securing said units together in the relation thus 90 controlled, and thereafter assembling with said units one or more other units in predetermined relations controlled by utilizing one or more of said last-named positioning surfaces and one or more positioning surfaces formed on said other unit or units and securing the parts together.

118. That improvement in methods of 95 making shoes which consists in providing a 100 plurality of units comprising an upper, an insole and one or more other bottom units each with one or more positioning surfaces formed and arranged to bear a predetermined relation to a characteristic of said unit, permanently securing said upper and insole together in a relation controlled by utilizing such positioning surfaces thereon, thereafter 105 assembling with said upper and insole said bottom unit or units in predetermined relations controlled by utilizing one or more of said last-named positioning surfaces and one or more positioning surfaces formed on said bottom unit or units, and permanently securing said bottom unit or units to said upper 110 and insole.

119. That improvement in methods of 115 making shoes which consists in preparing a plurality of units comprising the principal units of a complete shoe and providing each 120 of said units with one or more positioning surfaces for controlling its position in the shoe relative to the other units, building the shoe by positioning said units in relations controlled by engaging said positioning surfaces, 125 and independently of such positioning of the units inserting fastenings to secure the several units in their controlled positions.

120. That improvement in methods of 130 making shoes which consists in providing a

- plurality of shoe units comprising an upper and a plurality of bottom units each with one or more jig holes formed and arranged to bear a predetermined relation both to some selected contour of said unit and also to one or more of the jig holes formed on another of said units, said holes in each bottom unit being so located as to be unexposed in the finished shoe, utilizing such jig holes to control the relative positions of the units as they are assembled in the shoe and securing the units together in such controlled positions. 121. That improvement in methods of making shoes which consists in providing a plurality of different parts of a shoe each with one or more positioning surfaces located at a predetermined point or points unexposed on the exterior of the finished shoe, utilizing said positioning surfaces in successive steps in the manufacture of the shoe for locating adjacent parts of the shoe in standardized relation and after each of said steps securing parts of the shoe together while they are maintained in such relation. 122. That improvement in methods of making shoes which consists in providing a plurality of different parts of a shoe each with one or more positioning surfaces at a predetermined point or points unexposed on the exterior of the finished shoe and utilizing said positioning surfaces in locating parts of the shoe in standardized relation both to each other and to mechanism for operating upon one or more parts. 123. That improvement in methods of making shoes which consists in providing a plurality of different parts of a shoe each with one or more positioning surfaces at a predetermined point or points unexposed on the exterior of the finished shoe and utilizing said positioning surfaces in locating parts of the shoe in standardized relation to mechanism for securing the parts together while they are maintained in such relation. 124. That improvement in methods of making shoes which consists in providing a plurality of shoe units, including one or more bottom units, each with one or more positioning surfaces for controlling its position in the shoe relative to the other units, said positioning surfaces in the bottom units being so located as to be unexposed in the finished shoe, building the shoe by positioning said units in relations controlled by engaging said positioning surfaces, with said surfaces on the bottom units concealed by portions of the finished shoe. 125. That improvement in methods of making shoes which consists in providing a plurality of different parts of a shoe, including an outsole and a heel, each with a plurality of positioning surfaces for controlling its position in the shoe relative to the other parts, said positioning surfaces being so located as to be unexposed on the exterior of the finished shoe, utilizing said positioning surfaces in successive steps in the manufacture of the shoe for locating adjacent parts of the shoe in standardized relation and after each of said steps securing parts of the shoe together while they are maintained in such relation. 126. That improvement in methods of making shoes which consists in providing an outsole with a plurality of positioning surfaces, including a jig hole, so located as to be unexposed in the finished shoe, utilizing said surfaces to position the outsole in predetermined relation to other parts when assembling them in the shoe and securing the outsole to the other parts in such relation. 127. That improvement in methods of making shoes which consists in providing a plurality of shoe parts, including parts which are to be secured together with abutting or overlapping edges and parts which are to be secured together in superimposed relation, each with one or more positioning surfaces for controlling its position in the shoe relative to other parts, utilizing said positioning surfaces in successive steps in the manufacture of the shoe for locating in standardized relation parts of the shoe the edges of which abut or overlap and parts of the shoe which are superimposed, and securing the parts together while they are maintained in such standardized relation. 128. That improvement in methods of making shoes which consists in providing a short outsole and a rabbeted heel each with one or more positioning surfaces, shaping the rear end of the outsole and the shoulder of the rabbet of the heel each to fit the other, and utilizing said positioning surfaces for locating said parts on the shoe in standardized relation to each other and to other parts of the shoe, with the rear end of the outsole pressed firmly against the shoulder of the rabbet of the heel. 129. That improvement in methods of making shoes which consists in providing a plurality of different parts of a shoe, including an outsole and a heel, each with one or more positioning surfaces at predetermined points unexposed on the exterior of the finished shoe and locating said parts in standardized relation both to each other and to mechanism for operating upon one or more parts by engaging one or more of said positioning surfaces with complementary positioning elements associated with said mechanism and so located as not to interfere with operations to be performed on the shoe at any point on the exterior of the shoe. 130. That improvement in methods of making shoes, each including an upper, an insole, an outsole and a heel, which consists in positioning two of such parts relatively to each other and subsequently to one or more other parts by successive jiggling operations, after each of which operations parts are per-

manently secured together in the relations thus determined, the upper of the shoe being secured directly to the insole before the outsole is assembled therewith.

5 131. That improvement in methods of making shoes which comprises preparing separately a plurality of units comprising an upper, an insole, and one or more other bottom units by imparting to the toe of the upper 10 and to said bottom unit or units approximately the shape desired in the finished shoe and thereafter assembling and securing together the several units thus prepared.

132. That improvement in methods of 15 making shoes which consists in preparing a plurality of major units comprising the principal units of a complete shoe and during such preparation jiggling each such unit or a portion thereof by positioning it in predetermined relation to a shaping instrumentality and then applying pressure to one or more portions of the unit to impart thereto substantially the shape desired in the finished shoe, and assembling and securing together 20 the major units thus prepared.

133. That improvement in methods of 30 making shoes, which consists in preparing a plurality of major units comprising the principal units of a complete shoe by assembling and securing together for each major unit a plurality of minor units, applying pressure to one or more portions of each major unit to impart thereto substantially the shape desired in the finished shoe, 35 and assembling and securing together the major units thus prepared.

134. That improvement in methods of 40 making shoes, which consists in preparing a plurality of major units comprising the principal units of a complete shoe by assembling and securing together for each major unit a plurality of minor units, shaping each of the major units by pressure, providing each such unit with one or more 45 positioning surfaces formed and arranged to bear a predetermined relation to a surface or surfaces on another of said units, and building the shoe by assembling and securing the major units together in relations controlled 50 by utilizing said positioning surfaces.

135. That improvement in methods of 55 making shoes which consists in preparing a plurality of lots of standardized, interchangeable shoe units comprising the principal units of complete shoes and providing the units of each lot separately with like positioning surfaces formed and arranged to bear a predetermined relation to positioning surfaces of units of one or more other lots, making 60 said units into shoes by selecting for each shoe one unit from each lot and utilizing the positioning surfaces on the selected units to control the relation in which the units are assembled and secured in the given shoe.

65 136. That improvement in methods of

making shoes which consists in preparing standardized, interchangeable shoe units comprising upper, insole and outsole units and providing the units of each kind separately with like positioning surfaces formed 70 and arranged to bear a predetermined relation to positioning surfaces of units of one or more of the other kinds, accumulating stocks of said different kinds of units, and building shoes by assembling one unit of 75 each kind for each shoe and utilizing the positioning surfaces on the selected units to control the relation in which the units are assembled and secured in the given shoe.

137. That improvement in methods of 80 making welt shoes which consists in providing an insole with an upper-attaching rib in definite predetermined relation to its contour and with one or more other positioning surfaces, shaping an upper over a form and 85 assembling it with the insole while utilizing said surface or surfaces to position the insole relative to the form, securing the upper and a welt to said rib, and thereafter securing an outsole to the welt in a relation determined by 90 utilizing such a surface or surfaces on the insole and one or more positioning surfaces formed on the outsole.

138. As an article of manufacture, a sole 95 having at the rear of the shank portion a plurality of jig holes spaced lengthwise of the sole inside of the locations where fastenings are to be inserted for securing the sole to another part of a shoe.

139. As an article of manufacture, a welt 100 shoe insole having an upper-attaching rib and provided with one or more jig holes located in predetermined relation to said rib to cooperate with the rib in determining the relation of the insole to another part of a shoe. 105

140. As an article of manufacture, an insole having an upper-attaching rib and provided within its edge contour with one or more positioning surfaces in predetermined relation to said rib to co-operate with the rib 110 in determining the relation of the insole to another part of a shoe.

141. As an article of manufacture, a short 115 outsole of which both the rear and shank marginal portions are thinner than the central portion of the shank.

142. As a step product, an upper a portion 120 of which is molded to substantially the shape desired in the finished shoe and provided with one or more jig holes formed in predetermined relation to a characteristic of the upper and adapted for use in determining the relation of the upper to another part of a shoe.

143. As a step product, an upper having its 125 toe portion molded to substantially the shape desired in the finished shoe and provided in its heel portion with a plurality of jig holes adapted for use in determining the relation of the upper to another part of a shoe. 130

144. As an article of manufacture, an unattached heel comprising a base lift, a top lift and one or more other lifts all secured together, and having one or more jig holes 5 adapted to be utilized in positioning the heel in predetermined relation to a shoe, said jig holes extending from the heel seat face of the base lift but not into the top lift.
145. As an article of manufacture, an un- 10 attached heel comprising a plurality of lifts secured together and provided with a plurality of jig holes spaced lengthwise of the heel inside of the locations where the heel-attaching fastenings are to be inserted, said 15 jig holes being formed and arranged in predetermined relation to the edge contour of the heel so as to be utilized in positioning the heel on the shoe.
146. As an article of manufacture, a rabbeted heel including one or more short lifts and one or more relatively long lifts and having a jig hole in its rabbeted portion and another jig hole rearwardly of the first-named 20 jig hole.
147. As an article of manufacture, an un- 25 attached heel having an edge of predetermined contour and provided with one or more positioning surfaces formed by jig holes at predetermined points unexposed in the finished shoe.
148. As an article of manufacture, an un- 30 attached heel provided with a plurality of jig holes formed and arranged in predetermined relation to the final edge contour of the heel so as to be utilized to secure an exact 35 positioning of the heel for the performance of a manufacturing operation thereon.
149. As an article of manufacturing, an un- 40 attached heel having a plurality of jig holes formed and arranged in such predetermined relation to its edge contour as to ensure an exact, predetermined relation between the edge 45 contour of the heel and the contour of the counter portion of a correspondingly jigged shoe when the heel is assembled with the shoe with the aid of said jig holes.
150. As an article of manufacture, an un- 50 attached, rabbeted heel having an accurately formed positioning surface upon its breast, and a plurality of jig holes in exact, predetermined relation to said surface.
151. As an article of manufacture, a molded heel having a plurality of jig holes molded therein in exact, predetermined relation to 55 the periphery of the heel.
152. As an article of manufacture, a shoe sole having a substantially straight rear edge, and a jig hole located in predetermined relation to said edge and to the contour of 60 the sole.
153. A shoe bottom comprising a short sole and a heel having a rabbet in its breast into which the rear end of the sole fits, the heel and sole being provided with jig holes in predetermined relation to the contours of the 65 heel and sole, respectively, and so located as to be in alinement when the heel and sole are fitted tightly together.
154. A shoe bottom comprising a short sole and a heel, the heel having a rabbet in its 70 breast portion, into which the rear end of the sole fits, the heel and the rear end of the sole having complementary abutting surfaces, and the heel and the sole each having a jig hole in the same predetermined relation to said 75 surfaces.
155. A shoe bottom comprising a heel and a sole provided with aligned jig holes located in predetermined relation to their respective contours and having additional engaging 80 surfaces so disposed as to insure a predetermined, lateral location of the heel and sole and prevent relative angular movement thereof.
156. A shoe comprising a short sole and a 85 recessed heel overlapping the rear end of the sole, the heel and sole being provided with jig holes so located as to be in alinement when the heel and sole are fitted closely together and the heel being attached by nails, includ- 90 ing nails adjacent to the heel breast and passing through the rear end of the sole.
157. A shoe bottom comprising a short sole and a heel recessed at its breast end to receive the end of the sole, the heel recess extending 95 for the full width of the heel and having a substantially uniform, predetermined depth and the sole being shaped and reduced in thickness rearwardly of the heel-breast line to fit the recess in the heel.
158. A shoe comprising an upper, an insole, a short outsole, an insole-reinforcing member at the rear of said outsole, and a heel overlapping said outsole by substantially less than one half the length of the heel and permanently attached to the other parts by a plurality of fastenings located adjacent to the heel margin and extending through said reinforcing member.
159. A shoe comprising an upper, a sole, a 110 heel and a reinforcing plate at the heel portion of the sole, fastenings passing through the upper and the sole and clinched against said plate, and other fastenings passing through said plate and the sole and into the 115 heel to attach the heel permanently to the heel portion of the sole, the construction and arrangement being such that the plate serves as a holding means both for the fastenings which attach the upper to the insole and also 120 for the fastenings which attach the heel.
160. As an article of manufacture, an in- 125 sole-reinforcing plate composed of relatively hard and tough material penetrable by metallic fastenings, said plate also having substantially the peripheral contour of the heel end of an insole, being molded to conform to the concave surface of the heel portion of the insole and being provided with a beveled edge surface along its sides and convex rear por- 130

tion adapted to fit closely to the upper when the molded plate is in position in the shoe.

161. As an article of manufacture, an in-
sole-reinforcing plate having substantially
5 the peripheral contour of the heel end of the
insole with which it is to be assembled in the
manufacture of a shoe and provided with a
plurality of jig holes in predetermined rela-
10 tive to its contour for positioning the plate
relatively to the insole in the manufacture of
the shoe.

162. That improvement in methods of
making shoes which consists in molding the
15 toe and heel portions of an upper with in-
turned flanges, assembling the upper with an
insole and inserting the forepart of a last
into the molded toe of the upper while the
ball and shank portions of the upper and in-
20 sole are unconnected and then relatively mov-
ing the toe and heel portions of the upper long-
itudinally and relatively moving the heel
portion of the upper and the heel part of the

last heightwise to stretch the upper and com-
plete the mounting of the shoe in normal posi-
tion on the last, and thereafter permanently 25
securing the upper to the insole along their
ball and shank portions.

163. That improvement in methods of
making welt shoes which consists in molding
the toe and heel portions of an upper with in-
30 turned flanges, securing the toe end of an in-
sole to the toe end of the upper while leaving
portions of the upper and insole between the
toe and heel unconnected and inserting the
forepart of a last into the molded toe of the 35
upper and against the insole, stretching the
upper and completing the mounting of the
shoe on the last by relatively moving height-
wise the heel portions of the upper and of the
last. 40

In testimony whereof I have signed my
name to this specification.

GEORGE E. WARREN.
